UNITED STATES PATENT OFFICE.

MICHAEL MCANENY, OF DENVER, COLORADO, ASSIGNOR TO GEORGE R. DAVIS, OF CHICAGO, ILLINOIS.

COMBINED CHANGE-MAKER, CASH-REGISTER, AND INDICATOR.

SPECIFICATION forming part of Letters Patent No. 653,626, dated July 10, 1900.

Application filed September 18, 1899. Serial No. 730,914. (No model.)

To all whom it may concern:

Be it known that I, MICHAEL MCANENY, a citizen of the United States, residing at Denver, in the county of Arapahoe, State of Colorado, have invented certain new and useful Improvements in a Combined Change-Maker, Cash-Register, and Indicator; and I do hereby declare that the following is a full, clear, and exact description thereof, reference being had to the accompanying drawings, in which—

Figure 1 shows a perspective view of my machine; Fig. 2, a view of a vertical longitudinal section on line xx of Fig. 4; Fig. 3, a view of a transverse section on line yy of Fig. 2; Fig. 4, a view of a horizontal longitudinal section on line zz of Fig. 2 with some of the parts broken away for the purpose of showing the other parts below them; Fig. 5, a detail view, on an enlarged scale, partly in section and partly in side elevation, showing the mechanism for regulating the action of the extra five-cent feeding device, the parts being shown in position as when such device is not in operation; Fig. 6, a similar view showing the parts in position as when the extra five-cent feed device is in operation to feed out a coin; Fig. 7, a detail view showing a transverse section of the change-issuing mechanism, the section being on line $x'x'$ of Fig. 2; Fig. 8, a bottom plan view of the same; Fig. 9, a detail perspective view showing portions of the coin issuing and register and indicator actuating mechanisms; Fig. 10, a detail view showing, partly in section and partly in side elevation, the registering and indicating mechanisms; Fig. 11, a similar view showing portions of the registering and indicating mechanism with the parts in position as when a key has been moved through part of its throw to actuate the indicating and registering mechanisms; Fig. 12, a detail view, on an enlarged scale, showing in side elevation the registering mechanism; Fig. 13, a similar view of the same with the pinion, ratchet-wheel, and gearing for driving the worm-shaft removed; Fig. 14, a detail plan view of the means for rotating the register-pinion backward to cause registration; Fig. 15, a detail view, on an enlarged scale, showing the registering devices,

partly in section and partly in front elevation; Fig. 16, a plan view of the same; Fig. 17, a detail view showing, on an enlarged scale, in side elevation, the double-stop ratchets on the register-shaft with the back-motion stopping-pawl and forward-motion checking or brake pawl; Fig. 18, a similar view showing the register-shaft-driving ratchet-wheel, and Fig. 19 a detail plan view showing the relative arrangement of the indicator-rods and tablets thereon.

Letters of like name and kind refer to like parts in each of the figures.

The object of my invention has been to provide a machine for use in stores, restaurants, and the like which shall be a combined change-maker, cash-register and indicator, capable of not only registering and indicating the amounts of different purchases made, but of at the same time issuing the proper change to be returned to the customer when the amount given by the latter at the time of any purchase is greater than that required to be paid for such purchase; and with this end in view my invention consists in the machine and in the parts thereof constructed, arranged, and combined as herein-after specified.

The special purpose which I have had in view in making my present invention has been to provide a machine which is not only capable of registering and indicating properly the amount of any purchase made by a customer, but is so arranged and constructed that where the customer pays in an amount greater than that necessary for a purchase the movement of a single key corresponding to the amount of the purchase will cause such amount to be registered and indicated, so that the customer can see the indication and observe that the indication corresponds with his purchase, and will also cause to be issued an amount of change to be returned to the customer equal to the difference between what he paid in and the purchase made.

It has also been my purpose to make the machine readily and quickly adjustable, so as to make change on different bases, according to the amounts paid in by the customers. With this purpose in view I have, as will ap-

pear from the hereinafter-given description and drawings, arranged the machine so that it can readily be adjusted to issue change equal to the difference between a payment 5 and a purchase, whether the amount of such payment is two dollars, one dollar, fifty cents, or twenty-five cents.

It will be seen, further, that my machine is also capable of being quickly adjusted to 10 issue a nickel or five-cent coin whenever such an amount is required, and can be easily manipulated to deliver the proper change for other than two dollars, one dollar, fifty-cent or twenty-five-cent payments, or in case the 15 payment equals the purchase to simply indicate and register the amount of such purchase, whatever it may be, without operation of the change-issuing devices to cause the delivery of any change.

20 In the drawings, A A designate the two upright side plates of the casing of my machine, and A' designates the upright front plate, extending across between side plates A A and having in it the opening A² for the mouth of 25 the change-delivering hopper, the opening A³ below A² for the admission of the fingers of the hand placed to receive change from the hopper-mouth, and certain other openings 30 for the passage of keys, to be hereinafter described. The casing has also extending across within it the base-plate A⁴ for the support and guidance of the operative parts of the machine to be described, such base-plate being forwardly and upwardly inclined toward 35 the front of the casing and the lower back plate A⁵ extending upwardly and rearwardly at an angle from the rear edge of base-plate A⁴ to the lower edge of the upright back plate A⁶, which extending across between 40 such plates A A covers the rear side of the machine above plate A⁵.

The top of the casing consists of the top plate A⁷, inclined upward at a slight angle from a point near the front of the casing toward the rear of the latter, a door A⁸, hinged to the casing top plate at a point near its rear end, a short upright part A⁹, extending upward from a point just to the rear of the door A⁸ and provided with a sight opening A¹⁰, 45 through which any raised indicator-tablet can be seen, such opening being fitted with a sheet of glass in the way usual in cash registers and indicators, and a curved part A¹¹, covering over the space between part A⁹, the 50 top of back plate A⁶, and the raised rear portions of side plates A A.

While only the casing part A⁹ is shown as provided with a glass-closed indicator-display opening, it will be understood that a similar 55 glass-closed opening can be provided in the upper part of the back plate A⁶, as usual in cash registers and indicators.

The hinged door A⁸, which is for permitting access to, examination of, and resetting of 60 the register mechanism, to be hereinafter described, is shown as provided with a turn-button A¹² for locking the door shut; but it is to

be understood that any other suitable locking means for securing the door to prevent unauthorized manipulation of the registering devices can be employed instead, as desired, without involving any departure from my present invention, which has nothing to do with the form of such locking device or the means for preventing or permitting access to 75 the interior of the casing.

The casing of the machine, made up as described, is shown supported upon a base B, containing a moving drawer B', of the usual construction, having receptacles b b for coins and compartments b' b' b' for bills or banknotes. This drawer is not necessary to and has nothing to do with the operative mechanism or the operation of my machine and can be dispensed with or changed as desired. 85

Extending across the front of the machine above the upper edge of the front plate A' is the change-tray C, having the seven upwardly-extending half-tubes or semicylindrical receptacles c c to receive and hold the 90 different stacks of coins from which change is to be issued by the machine. As shown, this tray, having its front edge resting upon the top of casing-plate A and the rear edge of its upper end resting upon the front part of top plate A⁷, is tilted slightly rearward, so that its coin-receiving receptacles c c are inclined rearwardly a sufficient amount to insure the respective stacks of coins resting securely in them without danger of falling or being tilted 95 forward during use of the machine. This tray is detachably fastened in place in the casing by thumb-screws c' c' passing through the side plates A A of the casing and into lugs on or portions of the tray. As shown, 100 such tray has seven of the coin-holding receptacles or half-tubes c c, one of them—the one to the left of the series—being large enough to receive dollar-coins, the next one being adapted to receive half-dollars, and the 105 next quarter-dollars. The two succeeding tubes or receptacles to the right of the quarter-dollar one are adapted to receive nickels or five-cent pieces, while the remaining two on the right of the series are adapted to receive and hold ten-cent pieces. At the lower 110 ends of the half-tubes or coin-stack receptacles there are round openings c² c² through the base-plate of the tray, each opening being of such size as to just admit the downward passage of a coin from the respective stack in the half-tube or receptacle above. Below each of the openings c² there is a coin-support to keep the lower coin in the stack 115 above from dropping straight downward, such support standing at a distance below the lower end of the respective opening c², equal to or slightly greater than the thickness of one of the coins in the respective stacks, so that while such support acts to sustain 120 the stack of coins it will admit of the lowest coin in such stack being pushed forward off of the support by a device to be described. 125

These coin-supports are formed of a series of

plates C' C', attached by screws c^3 c^3 to the base-plate of the tray C, so as to leave narrow spaces c^4 c^4 between them, each of such spaces being in line with a point below the center of 5 one of the coin-openings c^2 , as shown best in Figs. 7 and 8. The front or outer edges of these plates are curved, so that their portions which project under the respective coin-openings present only crescent-shaped bearings 10 for the coins to rest upon, so that only a short sliding movement is necessary to carry the respective coins off of their supports and cause them to fall down within the casing into the hopper B², which, extending across below 15 the change-tray within the front of the casing, has its opposite sides inclined inward toward each other, and the downwardly and forwardly inclined coin-delivering mouth or chute b² extending outward through the opening A² in the front-plate A' of the casing.

As shown, (see Figs. 7 and 8,) the plates C' C' are secured to a portion of the base-plate of the change-tray which extends down below the planes of the bottoms of the coin- 25 openings c^2 c^2 , such portion of the base-plate being provided with grooves c^5 c^5 , each corresponding in size with and being situated directly over one of the spaces c^4 c^4 between plates C' C'.

30 The front side of the change-tray C is preferably, though not necessarily, closed with a sheet of glass C², through which the stacks of coins can be observed to see if they need replenishing at any time.

35 For feeding out the bottom coins from the several stacks in the change-tray I provide means which in their coin-engaging devices are like those set forth in my United States Patents Nos. 620,954 and 621,124, in that they 40 consist of coin-engaging dogs pivoted upon reciprocating actuating-slides, so that their forward or outer ends can swing upward into coin-engaging position and having springs to hold such ends normally raised and means 45 for limiting their upward swing, so that they can only stand high enough to engage and push out the bottom coins of the respective stacks.

The device for feeding out a nickel or five-cent coin from that one of the five-cent coin-tubes which is next to the twenty-five-cent tube is made just like the feeding device shown in my said patents, in that it consists of a coin-dog D, whose front end is adapted to 50 engage the rear side of the lowest coin in the stack, while its rear end is pivotally connected with the depressed part D' of the actuating-slide D² by a screw d, having its head situated in a recess d' in the dog and its shank 55 extending down through an opening in the bottom of the recess, which is made slightly larger than such shank, in order to allow swing of the dog up and down, and tapped into the depressed part of the slide. The upward 60 swing of the dog is limited by the screw d² on the dog passing through an opening in the slide and having its head adapted to en-

gage the under side of such slide when the dog has been swung upward to the limit of its movement. A spring d³, surrounding screw 70 d² and extending from the slide D² up into a recess d' in the dog, serves to hold the dog normally raised as far as the stop-screw d² will let it go.

The coin engaging and feeding devices for 75 the other coin tubes or receptacles differ from the one just described only in that the means for limiting the upward swing of each of the dogs is not merely a screw with its head below the respective actuating-slide, but is one 80 with a stop-shoulder d⁵ to engage the slide and which below that shoulder has a head d⁶, provided with a vertical slot d', for a purpose to be described. The dog-carrying slides having, as in the case of the similar slides 85 shown and described in my said other patents, the shoulders d⁸ d⁸ at the rear ends of their depressed parts to form abutments for the rear ends of the coin-feeding dogs when the latter are in operation and are being caused 90 to feed out coins by the movement of their respective slides are guided in ways a a in the base-plate A⁴, the rear ends of the slides being held down in such ways, while left free to reciprocate therein, by the cross-plate a', 95 secured to the base-plate, so as to extend across the same and overlap a portion of the slides seated in ways a a, as shown in Figs. 4, 5, 6, and 9. The coin-feeding dogs, being adapted to pass through the grooves c⁵ c⁵ and 100 the spaces c⁴ c⁴ between plates C' C', are of such thickness only that they can be swung down against the stress of their raising-springs, so that their upper sides will stand below the upper faces of plates C' C', forming the 105 coin-stack supports. With this construction all of the dogs when they have slid forward to feed out the respective coins and are returning cannot be hindered materially in their return by the engagement of the bottom 110 coins of the stack, for under pressure of such coins the dogs yield, so that all the weight of the coin-stacks is supported by the plates C' C', and the dogs can ride easily back under such stacks with only such friction against 115 the coins as is due to the light upward stress of their springs. By a downward pull on the slotted extensions d⁶, connected with the other dogs, except the one for feeding coins from what I call the "extra" five-cent coin 120 tube or receptacle—that is, the one nearest the twenty-five-cent tube or receptacle—such other dogs can be swung down before they are carried forward by their respective slides, so that their noses or coin-engaging ends will 125 be below the lowest coins in the respective coin-engaging slides, and consequently will not feed out any coins as the slides are moved forward. The purpose of this arrangement and construction will be described. 130

The extra five-cent slide for causing coins to be fed from the extra five-cent tube or receptacle has near its forward dog-carrying end a shoulder d⁹, adapted to be engaged by

the lug d^{10} on the supplemental slide D^3 reciprocating beside the extra five-cent slide in a suitable way in base-plate A^4 . The rear end of supplemental slide D^3 is, like the 5 corresponding end of slides D^2 D^2 , guided under cross-plate a' . To provide for holding its front end normally raised to lift its lug d^{10} above the plane of the shoulder d^9 on the extra five-cent slide, so that the supplemental 10 slide can reciprocate without actuating the latter, and at will letting the lug end of the supplemental slide down behind shoulder d^9 , so that forward sliding of the supplemental slide will cause a coin-feeding movement of 15 the extra five-cent slide, I pivot in bearings e e on the under side of the base-plate A^4 a rock-shaft E , having an arm E' extending up through an opening in the base-plate, under the forward portion of the supplemental 20 slide. A spring e' , attached to this rock-shaft and bearing against the base-plate, serves to keep the shaft normally turned to raise its arm E' up under the supplemental slide, so as to support the forward lug-carrying end 25 of the latter above the plane of the top of shoulder d^9 . On its other end the rock-shaft has a crank-arm E^2 , by which it may be rotated against the stress of its spring e' to depress the arm E' and allow the supplemental 30 slide to drop into position to carry its lug d^{10} down behind shoulder d^9 to cause the supplemental slide and extra five-cent slide to travel forward together as the supplemental slide is reciprocated toward the front of the 35 machine. The means for moving the crank-arm E^2 to so rotate the rock-shaft E will be described hereinafter.

Guided beside the dollar-feeding slide is another reciprocating slide D^4 for actuating the former very much as the extra five-cent slide is actuated by its supplemental slide, above described. This second supplemental slide, being guided in a suitable way in the base-plate and having its rearward end guided 45 under and held down by the cross-plate a' , has its front end free to be raised and lowered provided with a side lug d^{11} , adapted to engage a shoulder d^{12} on the dollar-slide when the slide end carrying it is down in the same 50 plane with the dollar-slide, but to travel back and forth above such shoulder when the supplemental slide end carrying the lug is raised. In Fig. 4 both supplemental slides are shown in the positions which they take when they 55 have been slid forward with their forward ends raised to carry their lugs above the shoulders on the adjoining coin-feeding slides.

To keep the dollar-slide-actuating supplemental slide D^4 with its lug-carrying forward 60 end normally raised to clear its lug from shoulder d^{12} , I provide the lever F , pivoted in ears f on the under side of the base-plate A^4 and having the upwardly-extending arm F' projecting up through a hole in the base-plate, 65 so as to engage and support with its upper end the forward end of the supplemental slide. This lever is normally held swung to raise

its arm F' , so as to elevate the forward end of supplemental slide D^4 enough to keep its lug d^{11} above shoulder d^{12} by the action of spring f' engaging the under side of base-plate A^4 and pressing down that part of lever F which is on opposite side of the lever-fulcrum from arm F' . The outer and lower end of this part of the lever is also provided with the weight 70 piece or head F^2 , which can be readily engaged and raised by the fingers inserted through the opening A^3 in the front plate A' of the casing as the hand is placed to receive coins in change from the mouth of hopper C . 75 It will be understood that this raising of piece or head F^2 causes arm F' to be lowered, so that the lug-carrying end of supplemental slide D^4 will descend to cause its lug d^{11} to engage the shoulder d^{12} on the dollar-slide 80 and make the latter slide travel forward with the supplemental slide and cause a dollar-coin to be fed from the dollar-stack as the latter slide is reciprocated toward the front of the machine. 85

Journalized in suitable bearings in the upright side frame-plates H H , secured to the opposite sides of the casing, is a rock-shaft I , extending across above the series of coin-delivering and supplemental slides. Such shaft 90 is connected with each of the supplemental slides D^3 D^4 by an arm I' , extending downward from the shaft and having its lower end situated between two shoulders i i on the respective slides, such shoulders engaging, respectively, the front and rear sides of the arm end, so that as the rock-shaft I is rocked forward and back on its axis each supplemental slide will be reciprocated toward and from the front of the machine. These shoulders i i I prefer to form, as indicated best in Figs. 5 and 6, by stamping or punching up portions of the slides, though they can be formed on or of the slides in any other way, as desired. The shaft I has also an upwardly-extending 100 arm I^2 , connected with spring I^3 , the other end of which is secured to a support on the casing forward of arm I^2 , so that the stress of the spring will always draw forward on arm I^2 to rock the shaft I and keep the arms 105 I' forced rearward to hold the supplemental slides normally retracted. This rock-shaft I is also connected with all of the other slides D^2 D^2 , so as to be rocked to move the supplemental slides forward each time that one of 110 the other slides is reciprocated toward the front of the machine and to retract such reciprocated slide when it has been released and left free to be moved rearward again. The connection of shaft I with each of the slides 115 D^2 D^2 consists of a downwardly-extending arm I^4 on the shaft for each slide and a shoulder i' on each slide, adapted to engage the rear side only of the lower end of the respective rock-shaft arm I^4 . With this construction as any slide D^2 is moved forward to feed a coin from the change-tray the engagement of the shoulder on such slide with the rear side of the respective arm I^4 on the rock- 120 125 130

shaft I will rock said shaft against the stress of its spring I³ to carry all of its arms I' I⁴ forward, moving the supplemental slides D³ D⁴, but leaving the other slides D² D² besides 5 the one just described as being moved at rest in their normal retracted positions, the arms I⁴ I⁴ for such slides passing idly forward over the latter. When the moved slide D² has been released by the power moving it, 10 the spring I³ by rapidly rocking the shaft I back again causes the said slide to be quickly retracted, because of the engagement of the arm on the rock-shaft with the shoulder i' on the slide. Also journaled in suitable bearings 15 in the side frame-plates H H are the transverse parallel rock-shafts K K, twenty in number, the series of such shafts beginning just forward of rock-shaft I and running forward to a point just to the rear of the coin or 20 change tray C. Each of these shafts K has an upwardly and rearwardly extending lever-arm K', whose upper rear end is connected with a key K², formed of a rod extending up through a suitable hole in the top plate A⁷ of 25 the casing and bearing on its upper end at some distance above such plate a finger-piece K³, having a flat table to be engaged by the finger to press the key down and a portion k, inclined forward and downward from the table, to receive the number or marking for the 30 respective key. As shown, each key-rod is connected with its lever-arm K' by a reduced portion of the rod passing through an opening in the lever-arm and having below the 35 latter a pin k', which, together with the shoulder on the rod at the upper end of the reduced portion, causes the key and lever-arm to move up and down together.

Nineteen of the finger-pieces K³ are marked 40 on their inclined front portions k with figures to correspond with different multiples of five cents, from five to ninety-five, inclusive, and the remaining finger-piece is marked to indicate one dollar.

45 For convenience in description I have on the drawings in Figs. 4 and 5 numbered the shafts K K consecutively from the front toward the rear of the series. These shafts are connected, through their lever-arms K' K' 50 and the rods of the keys, with the separate keys, as follows: shaft No. 1 with the dollar-key, shaft No. 2 with the five-cent key, shaft No. 3 with the sixty-five-cent key, shaft No. 4 with the forty-cent key, shaft No. 5 with 55 the ten-cent key, shaft No. 6 with the seventy-cent key, shaft No. 7 with the forty-five-cent key, shaft No. 8 with the fifteen-cent key, shaft No. 9 with the seventy-five-cent key, shaft No. 10 with the fifty-cent key, 60 shaft No. 11 with the twenty-cent key, shaft No. 12 with the eighty-cent key, shaft No. 13 with the fifty-five-cent key, shaft No. 14 with the twenty-five-cent key, shaft No. 15 with the eighty-five-cent key, shaft No. 16 with the 65 sixty-cent key, shaft No. 17 with the thirty-cent key, shaft No. 18 with the ninety-cent key, shaft No. 19 with the thirty-five-cent

key, and shaft No. 20 with the ninety-five-cent key.

The figures on the respective keys are to 70 correspond with the various amounts in multiples of five cents up to and including one dollar, which may be paid in by customers in making purchases.

In order that upon the pressing of any key 75 marked to correspond with the amount of any single purchase less than one dollar the proper change may be issued by the machine for return to the customer when the amount given by the customer is greater than that 80 required for the purchase and that the pressure of the dollar-key may cause a dollar to be fed out from the dollar coin-stack into the hopper, I connect the rock-shafts K K directly with the coin-feed-actuating slides D² D², 85 hereinbefore described, except the extra five-cent slide, as follows: The form of connection between a shaft and slide is in each case the same, consisting of a rigid downwardly-extending arm K⁴, adapted at its lower end 90 to engage the rear side of a shoulder d¹³ on the respective slide when the latter is in its normal retracted position. With this construction the forward swing of the arm, such as would be caused by pressing down on the 95 key-piece K³, which is connected with the rock-shaft K, carrying the arm, will cause the slide to be moved forward to compel the feeding of a coin from the respective half tube or receptacle of the change-tray; but 100 the arm will not interfere with or prevent such forward movement of the said slide when the latter is actuated by other means than that particular arm just described. The shoulders d¹³ d¹³ on the slides D² D² can be 105 formed like the shoulders i i on the supplemental slides D³ D⁴ by striking or driving up suitable portions of the slides or in any other desired way. Each rock-shaft K K is indirectly connected with the two supplemental 110 slides D³ D⁴ through the retracting rock-shaft I, having the arms I' I', engaging the shoulders i i on such slides, as hereinbefore described, and the arms I⁴ I⁴, engaging the front sides of shoulders i' i' on the slides D² D², and 115 the arms K⁴ K⁴ on the rock-shafts K K, engaging the rear sides of the shoulders d¹³ d¹³ on the latter slides, the construction being such that as any key is depressed to rock its rock-shaft K to move forward any slide D² 120 the two supplemental dollar and extra five-cent slide actuating-slides D⁴ D⁵ will always be moved forward, too, being subsequently retracted, with any moved slide, by the return movement of the slide-retractor rock-shaft I 125 under stress of spring I³.

130 Of the shafts K K, actuated, as described, by the keys K², No. 1, or the dollar-shaft, has only one arm K⁴ to engage the shoulder k' on the dollar-slide D². Shaft No. 2, the five-cent shaft, has four arms K⁴ to engage the shoulders d¹³ d¹³ on the fifty-cent, twenty-five-cent, and two ten-cent slides D² D², so as to cause ninety-five cents in coins to be is-

sued when the five-cent key is pressed. Shaft No. 3, the sixty-five-cent shaft, has two arms to engage the shoulders on the twenty-five-cent and a ten-cent slide, while shaft No. 4, the forty-cent shaft, has two arms to engage the shoulders on the fifty-cent and one ten-cent slide. The other rock-shafts K K have arms to engage lugs on the various coin-issuing slides D² D² as follows: shaft No. 5, four 10 arms to actuate a fifty-cent slide, a twenty-five-cent slide, a ten-cent slide, and a five-cent slide; shaft No. 6, two arms to actuate a twenty-five-cent and a regular five-cent slide; shaft No. 7, two arms to actuate a fifty-cent 15 and the regular five-cent slide; shaft No. 8, three arms to actuate the fifty-cent, twenty-five-cent, and one ten-cent slide; shaft No. 9, one arm to actuate the twenty-five-cent slide; shaft No. 10, one arm to actuate the fifty-cent 20 slide; shaft No. 11, three arms to actuate the fifty-cent, twenty-five-cent, and regular five-cent slides; shaft No. 12, two arms to actuate the two ten-cent slides; shaft No. 13, three arms to actuate the twenty-five-cent and two 25 ten-cent slides; shaft No. 14, two arms to actuate the fifty-cent and twenty-five-cent slides; shaft No. 15, two arms to actuate the regular five-cent and a ten-cent slide; shaft No. 16, three arms to actuate the twenty-five-cent, ten-cent, and regular five-cent slide; shaft No. 17, three arms to actuate the fifty-cent and two ten-cent slides; shaft No. 18, one arm to actuate a ten-cent slide; shaft No. 19, three arms to actuate the fifty-cent, one 30 ten-cent, and the regular five-cent slide; and shaft No. 20, one arm to actuate the regular five-cent slide.

With the arrangement and construction just above described it will be seen that upon 40 the pressure of any key marked with the amount of a purchase the machine can be made to issue as change to be returned to a customer coins to the amount of the difference between the purchase and one dollar, 45 the machine being arranged to normally issue different amounts of change required where the purchases are under a dollar in value and a dollar is paid in.

In order that the machine may be adapted 50 quickly and readily to give the proper change where the amount paid in by the customer exceeds the amount of his purchase, but is two dollars, fifty cents, or twenty-five cents instead of one dollar, I have provided certain 55 devices for regulating at will the amount of change issued to suit the amount of the payment made.

Where two dollars are paid in and the purchase is any amount less than a dollar, the 60 issue of the proper change is secured by pressing upon the head F³ of lever F, hereinbefore described, so as to lower the arm F' and let the supplemental slide D⁴ drop to bring its lug d¹¹ into engagement with the shoulder 65 d¹² on the dollar-slide D². The actuation of the key K², marked with the amount of the

purchase, will then cause the dollar-slide to be actuated to issue a dollar-coin, in addition to such coins as are issued, in the manner hereinbefore described by the actuation of 70 the other coin-slides caused by the engagement of the arms on the rock-shaft, which is connected with the key with the shoulders on said slides, and change will be delivered by the hopper for the payment on a two-dollar basis. 75

In order to provide for the making and issuing of the proper change for various payments on a fifty-cent or twenty-five cent basis and for the registration of any payments 80 without the issuing of any coin in change whenever such payments are exactly equal to the amounts of the respective purchases, I provide the following-described mechanism, connected with the pivoted feeding-dogs on 85 the slides D² D², except the extra five-cent slide hereinbefore described.

A rock-shaft L, extending across within the forward part of the casing and journaled in suitable bearings l l on the underside of base-plate A⁴, just to the rear of the series of slotted heads d⁶ d⁷ on the stop-screws d² d², connected with the pivoted spring-raised coin-feeding pawls or dogs D D, carried by all of the slides D² D², except the extra five-cent slide, has 95 attached to it the series of forwardly-extending arms l' l' l', extending through the slots d⁷ d⁷ d⁷ in the heads d⁶ d⁶ d⁶ on the screws connected with the two ten-cent and the regular five-cent feeding-dogs. It has also a similar 100 rigid arm l', projecting through the slot d⁷ in the head d⁶, connected with the dollar feeding-dog. The shaft L also has a rigid downwardly-extending arm l², by which it can be rocked, as desired, to lower and raise arms l' l' l' to 105 cause the latter to draw down the two ten-cent, five-cent, and dollar dogs and let the latter rise again to their normal raised positions, in which they are supported by their respective springs d³ d³. The construction 110 is such that as the shaft is rocked to depress its arms l' l' l' the latter will, by their engagement with the lower ends of the slots d⁷ d⁷ in the respective heads d⁶ d⁶, draw the coin-issuing dogs D D, connected with such heads, 115 down to carry and hold their coin-engaging noses or ends below the plane of the bottom coins in the respective stacks of coins in the change-tray, so that as the slides D² D², carrying said dogs, are reciprocated no coins will 120 be fed out by their dogs. The shaft L, with its arms l' l' l' l' engaging the slotted heads connected with the two ten-cent, the five-cent, and dollar feeding-dogs, forms a simple and efficient "cut-out" to cut the said dogs out 125 of operation at any time, as desired. A spring L', surrounding the shaft and engaging at its opposite ends the arm l² and the adjoining bearing l for the shaft, serves to press upon arm l², so as to keep the same pressed normally forward to hold the shaft with its arms l' l' l' l' raised to allow the coin-feeding dogs 130

of the two ten-cent, five-cent, and dollar slides to stand up in their coin engaging and feeding position.

To provide for rocking shaft L against the stress of spring L', I use the cut-out key L², consisting of a rod extending in through the front plate of the casing and bearing on its front or outer end a finger-piece l³, while within the casing its rod or shank passes through a hole in the lower end of arm l², being prevented from longitudinal movement through such hole by the pins l⁴ l⁴ passing through the rod in front of and to the rear of the arm l², respectively, the arrangement being such that while the key-rod and arm must move together as the rod is reciprocated longitudinally the rod can be swung up and down on the arm as a fulcrum without moving such arm. To the rear of arm l² the rod of this cut-out key is bent upward and then rearward, so that its rear raised portion is in position to engage the under side of the crank-arm E² on the rock-shaft E, hereinbefore described, which has the arm E' for normally raising the supplemental slide D³ for actuating the extra five-cent slide out of position to actuate the latter. The spring e' for holding the rock-shaft E in its normal position, with its arm E' raised and its crank-arm E² depressed, is strong enough to keep the rear or inner end of the rod or shank of the cut-out key l² normally depressed to raise the outer or front end of the key, as shown in Fig. 5. The finger-piece l³ has the horizontal outwardly-extending lower portion to be engaged by the finger, so as to depress said piece and raise the rear end of the key, as shown in Fig. 6, so as to raise the crank-arm E² and depress the arm E' to let the supplemental slide D³ drop into position to actuate the extra five-cent slide. A rearward swing of the arm l² of rock-shaft L, caused by pushing inward the cut-out key L², will, through the connections between such shaft and the dollar, five-cent, and two ten-cent dogs already described and the connections between the shaft and the fifty-cent and twenty-five cent dogs to be described, depress all of such dogs, so that no change will be fed out by the change mechanism no matter what one of the change-maker-actuating keys K² may be operated.

A sleeve M, journaled so as to rotate easily on the shaft L, has an arm m extending downward and then horizontally outward toward the side of the machine, its outer end passing just to the rear of and in contact with the arm l², and a horizontal forwardly-extending arm m', which passes through the slot d⁷ in the head d⁶ on the screw d², connected with the twenty-five cent feeding-dog D, just as and for the same purpose as the arms l' l' on the rock-shaft engage the slots in the heads of screws connected with the ten-cent, five-cent, and dollar feeding-dogs, as hereinbefore described. A cut-out key M² for rocking the sleeve is pivotally connected at its inner end

with a short arm on the horizontal part of arm m and at its outer front end, beyond the casing front plate, carries a suitable push-plate or finger-piece m². Another sleeve N is rotatively journaled on shaft L, between sleeve M and the arm l² on such shaft, and has the downwardly-extending arm n passing down behind and in contact with the rear side of the horizontal part of arm m on sleeve M and the forwardly-extending arm n', passing through the slot d⁷ in the head d⁶ of the screw d², which is connected with the fifty-cent coin-feeding dog. A spring N', engaging with one end a stationary bearing on base-plate A⁴ and with the other engaging arm n, serves to press such arm forward, so as to hold the sleeve normally with its coin-dog-depressing arm m' raised to leave the respective dog in position to feed out a coin from the fifty-cent stack as the slide carrying it is reciprocated. Because of the engagement of arm n with the rear side of the horizontal part of arm m on sleeve M the spring N' also serves to keep the latter sleeve normally rocked to raise its coin-feeding-dog-depressing arm m'. A push-key N² for actuating arm n and sleeve N against the stress of spring N' has its inner end pivotally connected with said arm n and extending forward from the latter through the front casing-plate, has on its front end a suitable push-head or finger-piece, as shown.

The operation of key L² when rocked upon its bearing in the arm l² of rock-shaft L has already been described fully. When so rocked to carry its rear end upward, it, through the described connections, causes the supplemental slide for actuating the extra five-cent slide to go into operation to cause a five-cent piece to be fed out of the extra five-cent tube or receptacle. When pushed longitudinally inward, it acts directly as a cut-out key, causing all of the coin-feeding dogs which are on the slides D² D², except that on the extra five-cent slide, which is normally not moved with any of the other slides, to be swung and held down out of operative position, so that no coins can be fed out by them from the change-tray. This it does because by moving the arm l² rearward it rocks the rock-shaft L to depress its coin-feeding-dog-depressing arms l' l' l' l' to draw the dogs of the two ten-cent, the regular five-cent, and the dollar slides down. This movement of arm l² also moves the arm m rearward to rock sleeve M and depress its arm m' to draw down the twenty-five-cent feeding-dog, and through the engagement of said arm m with the arm n on sleeve N also rocks the latter to depress its arm n' to lower the fifty-cent feeding-dog. The pressure of any key K², marked with the figure corresponding with the amount of any purchase, will now cause the issue of no coins or change from the change-tray, but will only cause registration and indication of the amount of the purchase made by mechanisms to be described, actuated by keys K² K². The cut-out key L² is therefore pushed in, as de-

scribed, only when the money paid in by a customer is equal to the amount of his purchase, and consequently no change is to be returned to him. When the amount paid in 5 is only fifty cents and the purchase is less, the cut-out key N^2 , next to key L^2 , is pushed in, so as to rock the sleeve N and cause the fifty-cent feeding-dog to be drawn down out of operative position. The operation of any 10 key K^2 representing the amount of a purchase less than fifty cents will then cause the proper one or ones of the series of slides D^2 D^2 which are to cause coins to be fed from the stacks of coins below fifty cents to be 15 moved to feed out the required change. When the amount of purchase by a customer is less than twenty-five cents and he pays in twenty-five cents, the cut-out key M^2 is pushed in, and because of the engagement of the arm 20 m with the arm n on sleeve N causes both sleeves M and N to be rocked to draw both the fifty-cent and the twenty-five cent feeding-dogs down out of operative position. When one of the keys K^2 , marked to 25 correspond with the amount of a purchase less than twenty-five cents, is then pressed, the proper one or combination of the ten and five cent slides D^2 D^2 will be actuated to push from the change-tray into the change-hopper 30 the necessary coin or coins to make up the difference between the amount of the purchase and the twenty-five cents paid in by the customer. To counterbalance the weight of the arms K' on the rock-shafts K and the 35 keys K^2 , connected with such arms, I provide each shaft K with a thin straight spring-wire k^2 , which, extending upward from the shaft, projects into one of the cuts k^3 k^3 in the plate K^4 , adjustably secured to one of the side plates 40 of the casing by screws k^4 k^4 passing through slots k^5 k^5 in the plate. The upper ends of springs k^2 k^2 pass up through the cuts k^3 k^3 into openings k^6 k^6 in the plate, as shown. With this construction as any key K^2 is 45 depressed to move any coin-delivering slide forward, and consequently to rock the slide-retracting rock-shaft I to carry its arms I^4 I^4 forward away from the lugs or shoulders i i on the unmoved slides, there will be no danger of any key K^2 falling because of the weight 50 of it and of the arm K' , connected with it. The support to which the front end of spring I^3 for actuating the retracting rock-shaft I is secured is the plate K^4 or a pin thereon. This 55 arrangement enables me to adjust the stress of the said spring upon the arm I^2 of the shaft I by moving the said plate forward or back on its adjustable connections with the casing side plate.

60 To provide for the registration and indication of amounts of the different purchases while the machine automatically issues the proper amounts of change, when the payments exceed the purchases in value, so that 65 the registration and indication of the amount of any purchase and the issue of change equal to the difference between the value of such

purchase and the amount of the payment therefor made by the customer will all be caused to take place by the movement of a 70 single one of the keys K^2 , the one marked to correspond with the amount of the purchase, I connect each key K^2 with registering and indicating devices, as hereinafter described.

Each rock-shaft K , which is connected, as 75 hereinbefore described, with one of the keys K^2 , so that depression of the key will cause the shaft to rock backward on its bearings, has an arm K^5 extending up from its upper side, and each of such arms is pivotally connected with the rear end of a reciprocating rod O , the arms K^5 K^5 being so arranged on the different rock-shafts as to be out of line with each other, so that the rods connected therewith can extend directly toward the rear 80 of the machine, lying in a series parallel with each other, as shown best in Fig. 4. There being twenty of these rods, or one for each rock-shaft K , the first one on the right of the series is connected with the arm K^5 on the 85 first or dollar rock-shaft. The rock-shafts for successive lower amounts from and including the ninety-five-cent shaft to and including the five-cent shaft are similarly connected with the successive rods O O in the series, 90 counting from the right to the left end of such series. On the rear end of each rod I secure a head O' for engaging and actuating the registering and indicating devices, such head being supported so as to slide easily 95 thereon on the transverse cross-bar O^2 , extending between the side frame-plates H' H' , secured to the side plates A A of the casing. These heads, having straight parallel sides, are placed close together, as shown, 100 the series of twenty heads being divided up into five series of four each, these smaller series being separated from each other by narrow spaces (see Fig. 4) to accommodate four arms P P , fixed on the rock-shaft P' , journaled above heads O' O' in suitable bearings 105 in the side frame-plates H' H' and carrying also the two outer arms P P , just beyond the opposite ends of the whole series of heads O' O' . On its under side each head has a shoulder o to strike the supporting-bar O^2 and limit the forward movement of the head and attached rod O . Each head has on its upper side an abutment o' to engage and move the cross-bar P^2 , carried by the arms P P P P on rock-shaft P' as the head is moved toward the rear 110 of the machine by reciprocation of its rod O , caused by depression of the key K^2 for operating the rock-shaft K , which is connected with this particular rod O , as hereinbefore described. From this abutment o' each head has a lower rearwardly-extending part passing under the bar P^2 and carrying on its rear end a raised part o^2 , the forward side of which is preferably inclined upward and rearward, as 115 shown in the drawings. The heads are made of such length that the rear ends of all of them will be in the same straight line, running transversely across the machine at right angles to 120

125

130

135

the heads when the latter are all in their normal forward positions, with their shoulders $o\ o$ resting against the bar P^2 . The abutments $o\ o$ on the respective heads $O' O'$ are arranged as shown best in Fig. 4—that is, so that the one on the head at the right of the series—that is, the one connected with the dollar rock-shaft K —stands close to the bar P^2 , carried by the arms $P\ P$ on rock-shaft P' , when the head is in its normal forward position, and the abutment on the next head stands a little farther away from the said bar P^2 . The distance between abutments on successive heads $O' O'$ and the bar P^2 increases regularly from the right to the left of the series of heads for a reason and purpose and by an amount to be described, the abutment on the head connected with shaft K , No. 2, or the five-cent shaft, being the farthest from bar P^2 , so that that head will have to pass over the greatest distance before its abutment strikes and moves the bar P^2 , and consequently actuates rock-shaft P' . Each head O' is provided with an overhanging part o^2 , extending rearward a short distance from the upper part of its abutment o' in a plane above the level of the top of the yielding bar P^2 , such overhanging part being a little longer than the thickness of bar P^2 and being slotted or notched vertically, as shown at o^3 , the rear end side of such slot or notch being preferably made flaring, as shown.

To secure lightness, the bodies of heads O' are preferably bored or hollowed or bored out from their abutments $o' o'$ forward, as indicated.

The rock-shaft P' , which is for actuating the registering mechanism to different extents as different heads $O' O'$ are forced rearward by the operation of the respective keys $K^2 K^2$, connected with them, has fixed to it a swinging segment-rack P^3 , provided with rack-teeth meshing with and driving pinion P^4 , journaled so as to rotate freely on the rock-shaft P^5 , which itself is journaled in suitable bearings on the side frame-plates $H' H'$. Secured to the hub of this pinion, so as to swing therewith as the pinion rotates, is an arm P^6 , carrying pivoted to its outer end a pawl p' , held by spring p^2 in engagement with the ratchet-wheel P^7 , fixed on shaft P^5 . In order to prevent the possibility of centrifugal action affecting in any way the operation of the pawl p' upon the teeth of the ratchet-wheel, I make such teeth, which, as shown, are twenty in number, on the side of the wheel, forming a crown-ratchet, and pivot the pawl to the arm P^6 by a pivot-pin p^3 , substantially parallel to a radius of the pinion P^4 . With this construction no matter how rapidly the arm P^6 may be swung the operation of the pawl can be in no way affected by centrifugal action to swing it into or out of engagement with the ratchet-wheel; but the pressure of the pawl against the ratchet-wheel is always uniform, being due to the stress of the pawl-spring p^2 . The pawl p' and the teeth on the ratchet-

wheel are so arranged that as the pinion is turned in the direction of the arrow in Fig. 12 by the swing of the segment-rack, caused by rearward movement of a head O' , the pawl will ride easily around over the ratchet-teeth without turning the ratchet-wheel or the shaft P^5 , upon which the wheel is fixed. As the pinion and arm P^6 , with its pawl p' , are very light they cannot have any considerable momentum however fast the pinion may be rotated by the segment-rack. Whatever momentum there would be is overcome by the action of the spring device which I use to rotate the pinion and pawl-arm backward when they have been turned forward and are allowed to turn back because of the removal of the actuating power previously applied to swing the segment-rack P^3 . Such service consists of a leaf-spring P^8 , attached at one end to a suitable fixed support p^4 and having its other end connected by a cord p^5 with a hub p^6 on the pinion P^4 . This hub has a cord-receiving groove p^7 extending around the hub from the point where the cord is attached in a diminishing spiral, as shown, so that as the cord is wound on the hub by the rotation of the pinion it will gradually approach nearer and nearer the axis of the hub and will consequently have less and less leverage for turning the hub and pinion or to resist such turning. With this construction the power of the spring to turn the pinion or resist its turning will be substantially uniform, because as the spring is bent more and more the effectual leverage which it has on the hub of the pinion is diminished, and as the spring straightens out and therefore loses power the cord, unwinding from the hub, has gradually more and more leverage to turn the latter and the connected pinion.

Attached to the rock-shaft P^5 are the two oppositely-turned ratchet-wheels $P^9 P^9$, having twenty teeth, those on one wheel having their abrupt sides facing in the direction opposite to that in which the shaft will be turned by the engagement of the pawl p' with the teeth of the ratchet-wheel P^7 as the pinion P^4 is rotated back by the spring device described and the segmental rack P^3 is returned toward its normal rearward position and the other ratchet-wheel P^9 having its twenty ratchet-teeth facing the other way. A spring-pressed pawl P^8 , pivoted on one of the plates H' , engages the former of these ratchet-wheels P^9 , so as to prevent any rotation of the shaft P^5 in a direction opposite to the arrow in Fig. 6—that is, the direction opposite to that in which pawl p' would rotate the shaft by its engagement with ratchet-wheel P^7 . Another pawl P^{10} , which I term my "brake" or "stop" pawl, engages the teeth of the other ratchet-wheel P^9 , fixed on shaft P^5 , to stop the rotation of the shaft under the influence of the engagement of the pawl p' on the arm of the spring-rotated pinion P^4 when the pinion and the segment-rack have been rotated back to their starting-points or to the positions which they

normally occupy when a key K^2 of the machine is not operated. This pawl P^{10} has its shank sliding in a longitudinal socket P^{11} in the swinging arm P^{12} , secured to the rock-shaft P' , which carries the segment-rack, and is pressed outward with reference to such arm by the spring P^{13} , its outward movement under stress of the spring being limited by a pin P^{14} on its shank engaging a slot P^{15} in the arm P^{12} . The rocking of the shaft P' swings this pawl P^{10} out of engagement with its ratchet-wheel P^9 as the shaft is turned to carry the segment-arm forward to rotate the pinion P^4 on the shaft and into the path of a tooth on wheel P^8 just as the rack completes its throw in the opposite direction, so that the ratchet-wheel P^9 , and consequently the shaft P^5 , will be suddenly brought to rest without any danger of overthrow due to momentum of the parts under the influence of the spring rotating pinion P^4 . As the pawl end is struck by one of the teeth on the ratchet-wheel P^9 , the pawl yields slightly against the stress of its spring P^{13} , so that there is no sudden or violent jar, and the action of the said spring then, when the parts have been brought to rest, pushes the pawl outward to its normal position, rotating the ratchet-wheel P^9 and shaft P^5 slightly backward. Secured to and rotating with shaft P^5 is the register-wheel R , having its periphery graduated into twenty equal parts by suitable graduation-lines numbered from "0" to "95," inclusive, the numbers increasing each time by five. An index-pointer R' , situated on a portion of the supplemental frame R^2 , secured to the adjoining side frame-plate H' , acts in conjunction with the graduations on wheel R , being so situated that as the pawl P' rotates the ratchet-wheel P^7 , and consequently the shaft P^5 , through the distance of one tooth on such ratchet-wheel the wheel R will be turned to cause a graduation-mark thereon to move away from the index-pointer and a new mark to be brought up to the latter. The rotation of ratchet-wheel P^7 through the distance of twenty teeth will then cause a full rotation of the register-wheel. The figures on the register-wheel from "5" to "95," inclusive, are intended to represent the different multiples of five cents in a dollar, so as to correspond with the markings on the keys K^2 K^2 , except the dollar-key. Attached to the shaft P^5 is also the gear-wheel R^3 , meshing with an equal-sized gear-wheel R^4 , secured on the worm-shaft R^5 , journaled in the supplemental frame R^2 and carrying the worm R^6 , meshing with and driving the worm-wheel R^7 , fixed on the vertical shaft R^8 , journaled in the frame R^9 , movably supported on frame R^2 , so as to be movable thereon to carry the worm-wheel into and out of engagement with the worm R^6 on shaft R^5 . The movable connection between frames R^2 and R^9 consists of screws r^r , tapped into frame R^2 and passing through longitudinal slots r^r in frame R^9 . For moving frame R^9 as desired to engage and disen-

gage the worm-wheel and worm I provide a lever R^{10} , pivoted to frame R^2 and connected with frame R^9 by a link R^{11} , such lever being made slightly yielding in a direction away from the plate of frame R^2 , to which it is pivoted, so that it can be passed over a stop-lug r^2 on the said plate as the lever is swung back and forth. The spring of the lever is sufficient to cause it to rest in engagement with the forward or rear side of this lug and hold the lever against swinging, and consequently retain the frame R^9 in the position into which it has been moved until the lever is grasped and sprung in enough to pass by the lug. The pitch of the described worm-gear is such that each time that the shaft P^5 , carrying the register-wheel R , is rotated through a full rotation the shaft R^8 is rotated through one-hundredth of a full turn. Secured on this shaft is a disk R^{12} , having its rim divided into one hundred equal parts by suitable graduation-marks, of which for clearness sake each fifth one is made longer than the others and is marked to indicate the number of dollars represented by such mark. The figures for these longer marks indicate consecutively greater and greater multiples of five, the figures running from and including "0" to 95 including "95." An index-pointer R^{13} for this disk, being fixed on a support on frame R^2 , extends slightly over the disk-rim, so as to act in conjunction with the graduations thereon to show how far the disk has been turned. As the described worm-gear causes this disk to rotate one one-hundredth of a full revolution each time that the register-wheel R makes a full turn the graduations on the disk can be considered as indicating dollars. A full revolution of disk R^{12} then represents one hundred dollars. To carry the registration still higher, so as to register a number of hundreds of dollars up to nine, I provide another disk R^{14} , to which each hundred, represented by a full turn of disk R^{12} , is transferred. Such disk R^{14} is secured on a short shaft R^{15} , journaled in the disk R^{12} , which shaft carries on its end below the latter disk the ten-toothed wheel R^{16} , whose teeth are adapted to be engaged by the fixed lug R^{17} on a standard on frame R^2 each time that the rotation of the disk R^{12} brings wheel R^{16} around to and past such lug. The rim of the wheel R^{14} is divided into ten equal parts by the graduation-marks numbered from "0" to "9," inclusive, and a fixed index-pointer R^{18} is secured on the top of shaft R^8 to act in conjunction with such graduations, as shown. With the described construction each time that the disk R^{12} makes a complete revolution to register one hundred dollars its movement causes the wheel R^{16} , because of the engagement of one of the teeth of toothed wheel R^{16} with lug R^{17} , to be turned to bring a new graduation up to the index-pointer R^{18} , thus registering each successive hundred dollars transferred from the registration of disk R^{12} . The wheel R^{14} can then register hundreds of dol-

lars up to nine, and the disk R^{12} , being capable of registering the dollars up to and including ninety-nine before a transfer or carrying of the registration to wheel R^{14} is caused, the 5 possible registration by my mechanism shown and described can be nine hundred and ninety-nine dollars and ninety-five cents.

When it is desired to set the register back to zero, this can readily be done after the 10 shifting of the worm-wheel R^7 out of mesh with the worm R^6 by the mechanism hereinbefore described. This will leave the disk R^{12} free to be rotated to carry it forward or 15 back to zero and leave the wheel R^{14} to be similarly turned to bring its zero-mark opposite its index-pointer. The register-wheel R can then be turned forward to zero by operating the proper key K^2 to cause it to be turned far enough to bring its zero-mark around 20 opposite its respective index-pointer. The abutments $o' o'$ on the different heads $O' O'$ are arranged to stand normally at such distances from the bar P^2 , carried by the arms $P P P P$ of the rock-shaft P' , that an equal movement 25 of the different heads will cause different amounts of travel of the bar P^2 , and consequently different amounts of rotation of the pinion P^4 and its pawl-carrying arm P^6 . In order to positively limit to its proper extent 30 the movement of bar P^2 each time that a key K^2 is operated, I provide the series of pivoted stops $S S$, one for each head O' , pivoted on a cross-shaft S' , supported by frame-plates $H' H'$. Such stops have their front portions 35 adapted to rest upon and be supported in an elevated position upon the raised rear ends of the heads $O' O'$, so that they will stand above the plane of the bar P^2 when the latter is in its normal unmoved position and 40 the heads $O' O'$ are unmoved, and in their normal forward positions are pivoted on the shaft S' in line with the notches or slots $o^3 o^3$ in the overhanging portions $o^2 o^2$ of the respective heads and are so shaped that when 45 the head supporting one of them is moved rearward a certain distance the stop will drop down into the path of the bar P^2 , as shown in Fig. 2. Its extreme forward end is formed to then constitute a positive stop to limit the 50 rearward travel of the bar under the pressure of the head thereon. These stops are of different lengths, the shortest one being at the right-hand end of the series and their lengths increasing as the other end of the series is 55 approached. The lengths of the respective stops are such that when any head has been moved far enough rearward to swing the bar P^2 , and consequently the rock-shaft P' and connected segment-rack P^3 , a sufficient distance 60 to carry the pawl p' on the arm P^6 , attached to pinion P^4 , back over a number of the ratchet-teeth on ratchet-wheel P^7 equal to the multiples of five, represented by the markings on the respective key which has been 65 moved to actuate the head, the stop for that head will engage and stop bar P^2 positively. In other words, the stops corresponding with

the different heads are of such length with regard to the abutments o' on the respective heads that as the heads are moved rearward 70 a certain distance, which is the same for all the heads, the stops will stop the bar P^2 when the latter has been moved far enough rearward to carry pawl p' back over numbers of the teeth on ratchet-wheel P^7 equal to the 75 multiples of five cents, represented by the markings on the keys connected with and operating the respective heads $O' O'$. As any key K^2 is operated the head O' connected therewith and moved therefrom will cause 80 the segment-rack to be moved to rotate the pinion and carry its pawl p' back over a number of teeth corresponding with the multiple or multiples of five represented by the marking on the key, and the return travel of the 85 pawl p' , under stress of the spring P^8 , will move the ratchet-wheel forward through the distance of that number of teeth over which the pawl passed on its first movement caused by the key. This rotates the shaft P^5 to turn 90 the register-wheel R through a number of its divisions equal to the number of teeth of ratchet-wheel P^7 over which the pawl has passed during its first-described movement preparatory to a registration. 95

It will be especially noticed that in my machine registration is not caused by the positive movement of the parts under power applied to any key and transferred to the registering device through the described connections, but only by the return movement of the pawl-carrying arm P^2 , traveling with pinion P^4 under stress of the spring P^8 , so that no matter how hard or sudden a key K^2 may be struck there is no danger of an overthrow 105 or overregistration by the registering device.

In order that whenever a key K^2 is operated to cause a registration, whether with or without the issuing of change by the machine, in the manner hereinbefore described, there will be displayed an indicator corresponding with the key moved, so that it can be seen whether or not the proper key has been moved by the operator, I provide the 110 following indicator mechanism having a separate indicator for each key carrying a tablet marked to correspond with the marking of the respective key—that is, with a figure or figures to agree with the amount of a purchase to be registered by said key: Journaled loosely upon the transverse shaft T , supported by frame-plates $H' H'$ above the series of pivoted stops $S S$, are the elbow-levers $T' T'$, one for each head O' , having their 115 pivotal openings engaging the shaft T at their angles and each having a downwardly-extending arm in the path of one of the heads O' and a rearwardly-extending arm connected with a vertical indicator-rod T^2 , so that 120 the rod and arm will move together as the lever is swung on the pivot-shaft T . For this purpose the rod can have a shoulder t resting on the upper side of the lever-arm 125 130

and a reduced portion t' extending down through a hole t^2 in such arm, with a pin t^3 passing through such reduced portion just under the arm, as shown in Fig. 2. Each 5 downwardly-extending lever-arm is provided with a longitudinal slot t^4 , through which the pivoted stop S for the respective head O' passes forward to such head. Each indicator-rod T^2 , being guided near its upper end in 10 a guide-hole t^5 in guide-plate T^3 , secured to the back plate A^6 of the machine-casing, carries on its upper end an indicator-tablet T^4 , marked to correspond with the marking of the respective key K^2 , to indicate the amount 15 of the purchase the registration of which is to be caused by the operation of the key. The indicator-rods are of such length that as the heads $O' O'$ corresponding to the separate rods are unmoved and in their normal 20 forward positions and the downwardly-extending arms of the levers $T' T'$ are resting against the rear ends of the respective heads $O' O'$ the indicator-tablets $T^4 T^4$ stand down below the display-opening A^{10} in the raised 25 part of the casing; but as any head O' is moved rearward to cause a registration and swings the engaged arm of the respective elbow-lever T' backward to raise the other arm of such lever and the indicator-rod connect- 30 ed therewith the tablet on such rod will be elevated to a position opposite the display-opening, so that the purchase-indicating figure or figures on it can be seen through such opening. For retaining each rod so raised in 35 its elevated indicating position until another key K^2 is operated to cause a new registration I provide the swinging-rod-retaining wing T^5 , pivotally supported at its opposite ends in the plates $H' H'$ and extending across 40 within the machine below the elbow-levers $T' T'$. Such wing, extending rearward from its pivotal portion, is provided with a weighted arm T^6 , adapted to hold the wing normally swung up into the path of the downwardly-extending arms of the levers $T' T'$ as such 45 arms are swung rearward to cause the levers to raise the indicator-rods connected with them. As any lever T' is swung by its respective head O' to carry its downwardly-extending arm rearward the end of such arm, riding over the upper face of wing T^5 , presses the latter downward until the end of the arm passes off of the rear edge of the wing. (See Fig. 11.) The weighted arm T^6 then swings the wing 50 quickly upward to cause its edge to stand in front of the lever-arm (see Fig. 2) and hold the latter in its retracted position, so that the other arm of the lever and the tablet-carrying indicator-rod connected therewith will be 55 maintained in their elevated position, to which they have been moved by the swing of the elbow-lever. The rearward and upward swing of another lever T' as its respective head O' is moved by the operation of another key K^2 60 to cause a new registration and operation of the machine will then, by the engagement of the downwardly-extending arm of such lever,

press the wing down again to disengage its edge from the arm of the previously-moved elbow-lever, (see Fig. 11,) so that such lever 70 will by the weight of the indicator-rod and tablet connected with it be quickly swung downward and forward again to cause the tablet on its rod to be dropped out of sight below the sight or display opening in the cas- 75 ing. As the movement of the elbow-lever being actuated is continued its wing-engaging arm finally passes off of the wing edge and the wing swings quickly up again to cause its edge to block the return swing of such engag- 80 ing arm and the newly-raised indicator-tablet is kept up in its elevated indicating position to show what key has been operated, so that the observer can at once see whether the machine has been operated to register his pur- 85 chase correctly.

From the foregoing description and the drawings it will be seen that my machine is so constructed that by the movement of a single one of the keys K^2 , the one which corresponds with the amount of a purchase made at any time, I secure not only registration and indication of the amount of said purchase, but also, where the amount paid in by the customer exceeds the amount of the purchase, is- 90 sue from the change-making part of the machine an amount of change for return to the customer equal to the excess of his payment over the amount of his purchase. 95

The operation of and manner of using my 100 machine, which will be understood from the hereinbefore-given description and the drawings, are briefly as follows: The machine being arranged, as hereinbefore indicated, to be normally adapted to make or issue change 105 on the basis of a dollar paid in, if a purchase less than a dollar in amount is made and a dollar is given in payment by the customer the operator presses on one of the keys K^2 , which is marked to correspond with the 110 amount of the purchase, and the machine will then register and indicate such amount, the register being turned the proper distance after the key is released and the pinion P^4 and the arm P^6 , connected therewith and carrying 115 the register-actuating pawl p' , are rotated by the spring P^8 and cord p^5 to return them to their several positions, and the indicator-tablet corresponding with the operated key having been raised during the downward move- 120 ment of the key to its elevated indicating position, so as to show through the display-opening in the casing by the pressure of the head O' , which is connected with such key, against the respective elbow-lever T' for moving the 125 indicator-rod carrying said tablet. The indicator retaining-wing T^5 , swinging up in front of the end of the elbow-lever arm, which has been passed back over it by the swinging of such lever, then locks the lever from swinging 130 downward and forward again and causes it to remain so as to retain the raised indicator to the position to which it has been elevated. Should the next purchase be the same in

value as the one just registered and indicated, a new registration will be caused by the rearward travel of the head O' , connected with the key, and the return movement of pinion 5 P^4 ; but the indicator will not be moved. The already-raised indicator for that key will remain in its elevated position, with its elbow-lever locked from swinging by the wing T^5 ; but should the following purchase be of a 10 value different from that one previously made the rearward pushing of the head O' , connected with the new key corresponding with the new purchase and being operated, causes another elbow-lever T' to be swung to 15 carry its downwardly-extending arm rearward over the wing T^5 , so as to depress the latter and cause its rear edge to pass down out of engagement with the previously-swung elbow-lever, so that such lever will swing for- 20 ward at once to allow the rod and indicator-tablet connected therewith to fall to take such tablet out of sight below the display-opening in the casing as the indicator-tablet connected with the newly-actuated elbow-le- 25 ver is being raised up into view. The paths of the lower arms of the elbow-levers with reference to the wing T^5 when raised are such that as each of such arms moves rearward it first engages the face of the wing at a point 30 well forward of its rear edge, so as to swing the wing enough to carry such edge well down below the paths of the lever-arms before the lever-arm moving over the wing reaches the wing's edge. This arrangement 35 makes it absolutely certain that any previously-raised indicator-rod will be dropped to depress its tablet out of sight before the raising of another rod and tablet is completed, so that there is no possible chance of any mis- 40 take in indication caused by a previously-raised indicator not dropping when another one is elevated to display position. While the registering and indicating devices are being operated, as described, by their respective 45 connections with the key K^2 , marked to correspond with the amount of a purchase made, the change-issuing device or devices connected with such key and operating as hereinbefore fully described will cause to be fed out 50 from one or more of the stacks of coins in the change-tray the proper coin or combination of coins to make up the amount of the difference between the dollar payment made by the customer and the amount or value of his 55 purchase. Such coin or coins dropping into the hopper B^2 are guided thereby into the hand of the operator placed below the hopper-mouth or into any suitable receptacle provided to receive the change to be given the 60 customer. Should a customer make a purchase less than a dollar in value and tender two dollars in payment, the head F^2 on lever F is raised to depress the arm F' of such lever and let the supplemental slide D^4 drop to 65 bring its lug d^{11} down behind shoulder d^{12} on the slide D^2 , which carries the dog for feeding out a dollar from the dollar-stack in the change-tray. The key K^2 , which is marked to correspond with the amount of the purchase, is then pressed, and besides causing 70 registration and indication of the new purchase it will not only cause the change-issuer to issue the proper coin or combination of coins to make up the difference between one dollar and the amount of the purchase, but 75 will also, because of the described connection of the supplemental slide D^4 with the dollar-feeding slide D^2 and with the retracting rock-shaft I and the connections between the tablet and the other slide or slides D^2 , ac- 80 tuated by the movement of the operated key K^2 , cause the dollar-slide to discharge a dollar, with such other change, into the hopper B^2 , so that the proper change to equal the difference between the customer's purchase and 85 the dollar payment will be delivered at one operation, ready to be given to the customer. The head F^2 of lever F can be readily reached and manipulated, as described, by the fingers of the hand placed in opening A^3 in the 90 casing below the hopper-mouth. Release of the head F^2 , allowing the lever F to be returned by its spring f and the weight of head F^2 to its normal position with its arm F' raised, immediately causes the supplemental 95 slide to be raised to carry its lug d^{11} up above the shoulder d^{12} on the dollar-slide D^2 and the machine is returned to its condition for issuing different amounts of change on the basis of a dollar payment. Should a purchase be 100 made less than fifty cents in value and only fifty cents be paid in, the cut-out key N^2 is pushed in to swing sleeve N and arm n' and so depress the fifty-cent-coin-feeding dog on the fifty-cent slide, so that as the slide is 105 moved the dog cannot engage and feed out a coin from the fifty-cent stack. The machine is now on a fifty-cent basis, and the operation of the proper key K^2 , marked to correspond with the amount of the purchase, will cause 110 the proper coin or combination of the coin-feeding slides for the twenty-five cent, one five-cent, and the two ten-cent stacks to be operated to feed out the necessary coin or coins to make the required change for fifty 115 cents to be returned to the customer. Simi- 120 larly should a purchase of less than twenty-five cents be made and twenty-five cents be tendered in payment the machine can be instantly changed to give change on the twenty- 125 five-cent-payment basis by pushing in the cut-out key N^2 , which because of the engagement of the arm m with arm n on the sleeve N causes not only its own sleeve M , but also sleeve N to be rocked, so that the arms m' and n' , connected, respectively, with such sleeves, will be depressed to draw the coin-engaging dogs D of the fifty and twenty-five cent feeding-slides D^2 D^2 down out of 130 coin-engaging position, so as to cut them out of action when the slides carrying them are moved. Actuation of the proper key K^2 , marked with a figure or figures to correspond with the amount of the purchase, will then

cause such a one or combination of the coin-feeding slides for the regular five-cent and the two ten-cent stacks of coins to be actuated that the coin-engaging dog or dogs on the 5 actuated slide or slides will feed out from the change-tray into hopper B² the proper coin or coins to make up the required change equaling the difference between the twenty-five-cent payment and the amount of the 10 purchase. Should the amount of payment tendered by the customer equal the amount of his purchase, so that no change is required to be returned, the cut-out key L² is pushed in, rocking the shaft L, because of the 15 engagement of the key with the shaft-arm l², and also the two sleeves M and N, because of the engagement of the shaft-arm l² with the arm m on the former sleeve and of the latter arm with arm n on sleeve N, so that the shaft- 20 arms l' l' l' l' draw down the coin-feeding dogs D D D D on the dollar, the regular five-cent, and the two ten-cent slides to cut such dogs out of action, and the arms m' and n' on the sleeves M and N similarly draw down and 25 cut out of action the coin-feeding dogs D D on twenty-five-cent and fifty-cent slides D² D². Operation of the key K² corresponding with any purchase will now cause actuation of the registering and indicating devices to make 30 proper registration and indication of the amount of the purchase without the feeding out of any coins by the change making or issuing part of the machine. Upon the release of the cut-out key L² the springs engaging the 35 shaft-arm l² and the arm n on sleeve N rock such shaft and the two sleeves M and N back to their normal positions, with their dog-depressing arms l', l', l', l', m', and n' raised to allow the respective coin-feeding dogs D to 40 rise under the stress of the elevating-springs d³ d³ into operative position for engaging and feeding out the bottom coins from the respective stacks of coins in the change-tray as the slides D D, carrying the dogs, are moved 45 toward the front of the machine. If a customer tenders a payment of seventy-five cents for a purchase less than that amount but greater than fifty cents, the proper registration and indication and issue of change may 50 be secured by first pushing in the cut-out key M² to cut the fifty-cent and twenty-five-cent feeding-dogs out of operation and then pressing the key K², which is marked to correspond with the amount of the purchase. 55 Such amount will then be registered and indicated, and the required change, being less than twenty-five cents, will be issued by the actuation of the proper one or ones of the slides D² for feeding coins from the regular 60 five-cent and ten-cent slides. When payments of other amounts than two dollars, one dollar, seventy-five cents, fifty-cents, or twenty-five cents are made, requiring the issue of only five cents in change, the cut-out 65 key L² is both pushed in and swung on its fulcrum on arm l², so that such arm and the shaft L, together with sleeves M and N, will

be swung to draw the coin-feeding dogs on the dollar, fifty-cent, twenty-five-cent, regular five-cent, and two ten-cent slides D² D² 70 down out of operative position, and the rock-shaft E will be rocked by the raising of the rear arm of rod of key L², so that the crank-arm E' on such shaft will be raised and the other crank-arm E² depressed, so as to allow 75 the supplemental slide D³ to drop to bring its lug d¹⁰ into engagement with the shoulder d⁹ on the extra five-cent slide D². Depression of any key K² carrying the marking corresponding with any purchase made will 80 then cause registration and indication of the amount of such purchase, and because of the connection of any slide D², moved by such key with the retractor-shaft I, and the connection of such shaft with the supplemental 85 slide D³ the latter slide will be moved to cause its lug d¹⁰ to drive the shoulder d⁹, and consequently the extra five-cent slide carrying such shoulder, forward to make the respective coin-feeding dog feed out five cents from the 90 extra five-cent stack. No other coins are fed from the other stacks on the change-tray because of the cutting out or depression of the coin-feeding dogs on all of the coin-slides but the extra five-cent one by the rocking of the 95 shaft L and sleeves M and N, caused by the inward sliding or pushing of the cut-out key L², as hereinbefore described. When it is desired to read off the registration of sales 100 during a certain period of time and to set the register back to zero, the hinged door A⁸ is unlocked and swung open, so that the figures on the register-wheel R, disk R¹², and disk R¹⁴, which are opposite the respective index-pointers, can be read off. The lever R¹⁰ is 105 then swung toward the rear of the machine to move the frame R⁹, carrying the worm-wheel R⁷, so as to disengage such wheel from worm R⁶. The disk R¹² can then be easily turned by the fingers to bring its zero-mark 110 around to a point opposite the index-pointer R¹³, and the disk R¹⁴, having been moved by the movement of frame R⁹ to carry its toothed wheel R¹⁶ away from the lug R¹⁷, can be similarly rotated to bring its zero-mark around 115 opposite index-pointer R¹⁸. The register-wheel R is set to zero by actuating that one of keys K² which carries a marking corresponding to the difference between the register-mark on wheel R which is opposite index-pointer R' and one dollar. This turns 120 the wheel to bring its zero-mark around to the latter index-pointer. The lever is then swung toward the front of the machine to move frame R⁹ to bring the worm-wheel R⁷ 125 into mesh again with worm R⁶, and the register is all ready for starting a new series of registrations of purchases.

Having thus described my invention, what I claim is—

1. In combination with a registering mechanism, adapted to register amounts of purchases of different values, a change-maker adapted to issue coins to make up different

portions of a certain predetermined sum of money, having coin-feeding devices normally ready to feed out coins when moved in coin-feeding direction, and connections between

- 5 the registering mechanism and the change-maker, whereby the operation of the registering mechanism, to register the amount of any purchase, causes the money-changer to issue a coin, or combination of coins, equal to the 10 difference between the amount of the purchase and the predetermined sum of money, substantially as and for the purpose described.

2. In combination with an indicating mechanism to indicate the amounts of different purchases of different values, a change-maker adapted to issue coins to make up different portions of a certain predetermined sum of money, having coin-feeding devices normally ready to feed out coins when moved in coin-feeding direction, and connections between the change-maker and the indicating mechanism, whereby, as the latter is operated, to cause indications of the amount of any purchase, the money-changer will be caused to issue a coin or combination of coins equal in value to the difference between the value of the purchase indicated, and the predetermined sum of money, substantially as and for the purpose described.

3. In combination with a cash-register and indicator, adapted to register and indicate the various amounts or values of different purchases made, a change-maker adapted to issue coins to make up different portions of a certain predetermined sum of money, having coin-feeding devices normally ready to feed out coins when moved in coin-feeding direction, and connections between such change-maker and the cash register and indicator, whereby, as the cash register and indicator is actuated, to cause registration and indication of the values of purchases made at different times, each time that a registration and indication of a purchase is made, the change-maker will be actuated to issue a coin, or combination of coins, equal in value to the difference between the price or value of the purchase being registered and indicated and the predetermined sum of money, substantially as and for the purpose described.

4. In combination with a register, adapted to register the amount or value of a purchase made, a source of supply of coins, each equal to the difference between the value of the purchase and a certain predetermined sum of money, and means for feeding out a coin at a time from the source of supply, actuated each time that the register is actuated to register the purchase, and normally ready to feed out a coin when moved in coin-feeding direction, substantially as and for the purpose described.

5. In combination with an indicating mechanism, adapted to indicate the amount or value of a purchase made, a source of supply of coins, each equal to the difference between

the value of the purchase and a certain predetermined sum of money, and means for feeding out the coins, one at a time, from the 70 source of supply, connected with the indicating mechanism, so as to be actuated to feed out a coin from the source of supply, each time that the indicator mechanism is operated, and normally ready to feed out a coin 75 when moved in coin-feeding direction, substantially as and for the purpose described.

6. In combination with a register and indicator, arranged to register and indicate the amount or value of a purchase made, a source 80 of supply of coins, each equal in value to the difference between the purchase made and a certain predetermined sum of money, and means for feeding out the coins one by one, connected with the registering and indicating 85 mechanism, so as to be actuated therewith to feed out one of the coins, each time that the register and indicator are caused to register and indicate a new purchase, and normally ready to feed out a coin when moved in coin-feeding direction, substantially as and for the purpose described.

7. In combination with a register, to register the amount of a purchase made, two or more sources of supply of coins of such denominations, that single coins taken from the separate source of supply will, together, be equal in value to the difference between the amount of purchase which the register is adapted to register and a predetermined sum 100 of money, feed devices for feeding coins singly from the separate sources of supply, normally ready to feed out coins when moved in coin-feeding direction, and connections between such devices and the register, whereby 105 each time that the latter is actuated to cause registration of a purchase, the coin-feeding devices will also be actuated to feed out a combination of coins equal to the difference between the value of the purchase and the 110 said predetermined sum of money, substantially as and for the purpose described.

8. In combination with an indicator, to indicate the value of a certain purchase, each time that it is operated, means for operating 115 it, two or more sources of supply of coins of such denominations, that single coins taken from the separate sources of supply will, together, be equal in value to the difference between the amount of the purchase to be indicated and a certain predetermined sum of money, means for feeding out the coins singly from the separate sources of supply, normally ready to feed out coins when moved in coin-feeding direction, and connections between such means and the means for operating 125 the indicator, whereby, as the latter is operated, the coin-feeding means will also be actuated to feed coins out from the sources of supply, substantially as and for the purpose 130 described.

9. In combination with a cash-register and indicator, for registering and indicating the amount of value of a purchase made, means

for actuating the same to cause registration and indication of a purchase, two or more sources of supply of coins of such denominations, that single coins taken from the separate sources of supply will, together, be equal in value to the difference between the amount of the purchase being registered and indicated, and a certain predetermined sum of money, means for feeding out coins from the separate sources of supply, normally ready to feed out coins when moved in coin-feeding direction, and connections between the means for actuating the registering and indicating devices, and the coin-feeding means, whereby, as the registering and indicating devices are actuated to cause a registration and indication of the amount of a purchase, the coin-feeding means will be caused to act to feed out coins singly from the respective sources of supply, substantially as and for the purpose described.

10. In combination with a register, adapted to register the amount of a purchase made, means for causing actuation of such register, a source of supply of coins, each equal in value to the difference between the price or value of the purchase being registered and a certain predetermined sum of money, a feed device for feeding out such coins from the source of supply, normally ready to feed out a coin when moved in coin-feeding direction, connections between such device and the means for causing actuation of the register, whereby movement of the register-actuating means causes the coin-feeding device to be operated in a direction to feed out a coin from the source of supply, and means for throwing, at will, the coin-feeding device out of position, to engage and feed out a coin, as it is moved, substantially as and for the purpose described.

11. In combination with an indicating mechanism, to indicate the amount of a purchase made, means for operating such mechanism, a source of supply of coins, each equal in value to the difference between the amount of the purchase indicated, and a certain predetermined sum of money, a feed device to feed out the coins from the source of supply, having its coin-engaging part adapted to be moved into and out of position, to engage and feed out a coin, as the device is moved, means for normally moving such part into operative position, means for moving it, at will, out of such position, and connections between the feed device and the means for operating the indicator, whereby such means both operates the indicator and moves the coin-feeding device in a direction for feeding out a coin from the source of supply, substantially as and for the purpose described.

12. In combination with a cash-register and indicator, for registering and indicating the amount of a purchase made, means for operating the same, to cause registration and indication of the amount of a purchase, a source of supply of coins, each equal in value to the

difference between the purchase registered, and a certain predetermined sum of money, a coin-feeding device having a coin-engaging part made movable into and from a position to engage and feed out a coin from the source of supply, as the device is moved in the direction of the latter, means for normally moving such part into operative, coin-engaging position, means for moving it, at will, out of such position, and connections between the coin-feeding device and the means for operating the cash register and indicator, whereby, power applied to operate the register and indicator, causes the coin-feeding device to move in a direction for feeding out a coin from the source of supply, substantially as and for the purpose described.

13. In combination with a cash-register, adapted to register the amount of a purchase made, means for causing actuation of such register, a source of supply of coins, each equal in value to the difference between the price or value of the purchase registered, and a certain predetermined sum of money, a feed device, to feed out the coins from the source of supply, having its coin-engaging part adapted to be moved into and out of position, to engage and feed out a coin as the device is moved, a spring to hold such part normally in its operative position, means for moving it, at will, out of such position, and connections between the feed device and the means for operating the register, whereby such means both causes actuation of the register, and movement of the feeding device, in a direction to feed out a coin from the source of supply, each time that the register is actuated, substantially as and for the purpose described.

14. In combination with a cash-indicator mechanism, to indicate the amount of a purchase made, and means for operating the same, a source of supply of coins, each equal in value to the difference between the amount of the purchase indicated, and a predetermined sum of money, a feed device for feeding out a coin from such source of supply, each time that the indicator mechanism is actuated to cause indication of a purchase, such feed device having a movable coin-engaging part, adapted to be moved into and out of operative position, to engage and feed out a coin from the source of supply, as the feed device is moved, a spring normally holding such part in operative position, means for moving that part, at will, out of operative position, and connections between the feed device and the means for actuating the indicator mechanism, whereby such device is caused to move in a coin-feeding direction, each time that the indicator mechanism is operated to indicate a sale, substantially as and for the purpose described.

15. In combination with a cash-register and indicator, to register and indicate the amount or value of a purchase, and means for operating the same, a source of supply of coins,

each equal in value to the difference between the amount of the purchase registered and indicated, and a predetermined sum of money, a feed device for feeding out the coins from the source of supply, connected with the means for actuating the registering and indicating devices, so as to be operated each time that they are operated to register and indicate a purchase, such feed device having its coin-engaging part made movable into and out of operative position to feed out a coin from the source of supply, as the device is moved, a spring holding such part normally in operative position; and means for moving such part, at will; out of operative position, so that, as the feed device is moved, no coin will be fed by it from the source of supply, substantially as and for the purpose described.

16. In combination with a cash-registering mechanism, a series of keys for actuating the same, adapted to cause the registering mechanism to register purchases of different values, a change-maker having a series of sources of supply of coins, and a series of feed devices to feed out coins from the different sources of supply, each device having a coin engaging and feeding part adapted to be moved into and out of operative position to feed out a coin from the respective source of supply as the device is moved, yielding means to hold such part normally in operative position, means for moving the coin-engaging parts, at will, out of operative position, and connections between the series of coin-feeding devices and the series of keys, whereby, as any key is operated to actuate the register mechanism to register a certain purchase, the coin-feeding device or devices, for issuing a coin or combination of coins equal to the difference between the value of the purchase registered, and a predetermined sum of money, will be actuated, substantially as and for the purpose described.

17. In combination with a cash-indicator mechanism, having a series of indicators to indicate purchases of different values, and a series of keys to actuate the different indicators, a change-maker having a series of sources of supply of coins, and feed devices for feeding out coins from the respective sources of supply, each having its coin-engaging part made movable toward and from its operative position, to engage and feed out a coin from the respective source of supply, as the feed device is moved, means for yieldingly holding such part of each device normally in operative position, connections between the separate keys and the coin-feeding devices, whereby, as any key is moved to actuate an indicator, one or more of the coin-feeding devices will be moved in a direction to feed from one or more of the sources of supply of coins one or more coins to make up the value of the difference between the purchase indicated and a predetermined sum of money, and means for depressing the coin-engaging parts of the feed devices, at will, to move them out

of operative position, substantially as and for the purpose described.

18. In combination with a cash-register, to register purchases of different values, and an indicator, having a series of indicating devices to indicate the values of different purchases, a series of keys connected with the register and indicator, so as to cause purchases of different values to be registered and indicated, as the different keys are operated, a change-maker having a series of sources of supply of coins, and a coin-feeding device for each source of supply, having its coin-engaging part made movable into and out of operative position, to engage and feed out a coin as the respective feed device is moved and normally in operative position, means for moving, at will, each coin-engaging part out of operative position, and connections between the register and indicator actuating keys, and the coin-feeding devices, whereby, the movement of any key will cause the movement of a feed device, or combination of feed devices, in a direction for feeding a coin or combination of coins, amounting in value to the difference between the value of the purchase caused to be registered and indicated by the movement of the key, and a predetermined sum of money, substantially as and for the purpose described.

19. In combination with a series of sources of supply of coins, and a series of feed devices to feed coins out from such sources, means for throwing all of such devices out of operation, while allowing them to move, an extra source of supply of coins, a feed device therefor, and means for moving such device connected with the other feed devices, so as to be moved as any one of the latter is moved, and means for connecting and disconnecting the extra coin-feed device from its actuating means, at will, substantially as and for the purpose described.

20. In combination with a series of sources of supply of coins, and a series of coin-feeding devices, to feed out coins therefrom, a series of keys connected with these coin-feeding devices so as to cause them to feed out coins, and combinations of coins, equal in value to the difference between various purchases made and a predetermined sum of money, an extra source of supply of coins, a feed device for the same, operative connections between this feed device and the other feed devices for actuating the former device when any one of the latter devices is actuated, means for throwing such connections into and out of operation, at will, and means for throwing all of the other feed devices out of operation, to feed coins, while leaving them capable of being moved, when the extra coin-feeding device is in operation, substantially as and for the purpose described.

21. In combination with a series of sources of supply of coins, and a series of feed devices, to feed coins out from such sources, each having its coin-engaging part made mov-

able into and out of operative position, to engage and feed out a coin from the respective source of supply, means for holding such parts normally up in operative position, and 5 means for moving them all out of such position, at will, an extra source of supply of five-cent coins, a feed device for feeding out the coins from such source, a moving slide connected with the feed devices of the other 10 sources of supply of coins, so as to be moved each time that one of the other feed devices is moved, and means, whereby the slide can be, at will, connected with the extra five-cent feeding device, to actuate the same, substantially as and for the purpose described.

22. In combination with a series of sources of supply of coins, a series of feeding-slides therefor, each having a coin-feeding dog pivoted on it, and normally held up in coin-engaging position by a spring, means for drawing down all of the dogs out of operation, at will, an extra source of supply of five-cent coins, a feeding device for feeding coins therefrom, a slide adapted to be connected with, 20 and disconnected from, this feed device, connected with the other feed devices, so as to be moved each time that one of the latter is moved, and means for holding the slide normally, out of engagement with the extra five- 25 cent feeding device, adapted to be moved to allow the slide to go into engagement with such feed device, substantially as and for the purpose described.

23. In a change-maker, in combination with 30 a series of sources of supply of coins, and a series of feeding devices, to feed out coins from the respective sources of supply, such feed devices having their coin-engaging parts made movable into and from operative position to engage and feed out coins from the respective sources of supply, yielding means for holding said parts normally in operative position, means for moving them, all at will, out of such position, a series of movable parts 40 to actuate the coin-feeding devices, which are connected with the feed devices, so that the movement of each part will cause the operation of one or more of the coin-feeding devices, to feed out a coin, or coins, to the 45 value of some multiple of five cents, an extra source of supply of five-cent coins, a feed device therefor, a movable slide, means whereby such slide can be connected with, and disconnected from, the extra five-cent feed device, and connections between the slide and the other coin-feeding devices, whereby, as any one 50 of the latter is moved by its connected, actuating part, the slide will be moved, substantially as and for the purpose described.

24. In combination with a series of sources of supply of coins, a series of slides, carrying dogs to engage and feed out coins from the respective sources of supply, yielding means for holding such dogs in operative position, 60 to engage and feed out coins, as the slides are moved, means for drawing all of the dogs down out of such position, at will, an extra

source of supply of five-cent coins, a feed-slide therefor, having a coin engaging and feeding part, and a shoulder, a supplemental slide, having a lug to engage the shoulder on the extra five-cent feed-slide, and itself connected with the other feed-slides, except the extra five-cent one, so that the movement of any of such other feed-slides, will move the supplemental slide, and means for holding the latter slide normally in position to have its lug disengaged from the shoulder, on the extra five-cent feeding-slide, adapted to be moved, to cause the supplemental slide to move, to bring its lug into engagement with the shoulder on the extra five-cent slide, substantially as and for the purpose described.

25. In combination with a series of sources of supply of coins, a series of feed-slides 85 therefor, each having a movable, coin-engaging dog, springs to hold such dogs normally in operative position, to engage and feed out coins as the respective slides are moved, means for drawing down all of such dogs, at will, to 90 take them out of operative position, a supplemental slide connected with each of the other slides, so as to be moved as any one of them is moved, and having a lug, an extra source of supply of five-cent coins, a feeding device 95 therefor, having a shoulder to be engaged by the lug on the supplemental slide, and means for causing the supplemental slide to be moved into and out of position to bring its lug into engagement with such shoulder, substantially as and for the purpose described.

26. In combination with a register, adapted to register purchases of different values, in multiples of five cents, a series of actuating parts connected with such register, to cause 105 it to register different multiples of five cents, as the different parts are moved, a change-maker having a series of sources of supply of coins, from which different coins and combinations of coins, equal to different multiples 110 of five cents, can be fed out, a series of feeding devices, one for each source of supply, and each having a movable coin-engaging part, adapted to be moved into and from operative position, to engage and feed out a coin, means for holding such coin-engaging parts normally in operative position on the respective feed devices, means for moving them, at will, out of such position, an extra source of supply of five-cent coins, a feed device, a supplemental slide, connected with the other feed devices, so as to move as any one 115 of them is operated, and adapted to be coupled with, and uncoupled from, the extra five-cent feeding device, means for holding it normally uncoupled therefrom, and causing it to be coupled therewith, at will, and connections between the feeding devices of the sources of supply of coins, except the extra five-cent device, and the series of parts for 120 actuating the register, whereby, the movement of each part, to cause the register to register an amount equal to a multiple of five cents, will cause a coin, or combination of

coins, to be issued by one or more of such feed devices, to equal in value the difference between the multiple of five cents registered and a predetermined sum of money, substantially as and for the purpose described.

27. In combination with an indicator, having a series of indicating devices, to indicate different amounts of cash, equal to different multiples of five cents, a series of movable parts, to cause actuation of the different indicating devices, a series of sources of supply of coins, a series of feed devices therefor, for feeding the coins out of the different sources of supply, each of such feeding devices having a movable, coin-engaging part, adapted to be moved into and out of operative position in the device, means for normally holding such part in operative position, means for moving all of the coin-engaging parts out of operative position, at will, connections between the respective parts for actuating the different indicating devices and the coin-feeding devices, whereby, the movement of any one of such indicator-actuating parts will cause a coin-feeding device, or combination of feeding devices, to issue a coin, or combination of coins, equal in value to the indication of the indicator moved, an extra source of supply of five-cent coins, a coin-feeding device therefor, a slide connected with the other coin-feeding devices, so as to move with any of them that may be moved, adapted to be coupled with, and uncoupled from, the extra five-cent feeding device, and means for causing it to be coupled with, and uncoupled from such device, at will, substantially as and for the purpose described.

28. In a combined cash-register and change-maker, in combination with a registering mechanism and change-making mechanism, normally in condition to make change upon being operated, means for throwing the latter mechanism out of operation, at will, without stopping the operation of the registering mechanism, substantially as and for the purpose described.

29. In a combined cash-indicator and change-maker, in combination with an indicating mechanism and change-making mechanism, normally in condition to make change upon being operated, means for throwing the change-making mechanism out of operation, at will, without stopping the operation of the indicating mechanism, substantially as and for the purpose described.

30. In a combined cash register and indicator and change-maker, in combination with the registering mechanism, the indicating mechanism, and the change-making mechanism, normally in position to, make change upon being operated, means for throwing the change-making mechanism out of operation, at will, without stopping the operation of the registering and indicating mechanisms, substantially as and for the purpose described.

31. In a combined cash-register and change-maker, in combination with the registering

mechanism, and the change-making mechanism, normally in condition to make change upon being operated, a key, connections between such key and the two mechanisms, whereby a motion of the key actuates both, and means for throwing the change-making mechanism out of operation, at will, while leaving the registering mechanism capable of operation by the key, substantially as and for the purpose described.

32. In a combined cash-register and change-maker, in combination with the registering mechanism for registering the amounts of a purchase made, and the change-making mechanism, for issuing an amount of change equal to the difference between the amount of the purchase and a predetermined sum of money, normally in position to issue such change upon being operated, means for operating the two mechanisms, and means for throwing the change-making mechanism out of operation without stopping the operation of the registering mechanism, substantially as and for the purpose described.

33. In a combined cash-register and change-maker, in combination with the registering mechanism for registering purchases of different amounts, means for actuating such registering mechanism, a change-making mechanism, normally in position to act, for issuing different amounts of change, equal to the difference between the amounts of the purchases registered and a predetermined sum of money, connections between the change-making mechanism and the register-actuating means, whereby the movement of such means to actuate the register will also actuate the money-changing mechanism, and means for throwing the latter mechanism out of operation without stopping the operation of the registering mechanism, substantially as and for the purpose described.

34. In a combined cash-register and change-maker, in combination with the registering mechanism for registering purchases of different amounts, means for actuating such registering mechanism, a change-maker for issuing different amounts of change, equal to the difference between the different amounts of purchases registered and a predetermined sum of money, connections between the change-making mechanism and the register-actuating means, whereby movement of such means to actuate the register will also actuate the change-making mechanism, to cause it to, issue a coin or coins equal in value to the difference between the value of the purchase being registered and the predetermined sum of money, means for throwing the said change-making mechanism out of operation without stopping the operation of the registering mechanism, an extra source of supply of coins,

a feed device to feed coins therefrom, connections between such feed device and the means for actuating the registering mechanism and change-maker, and means for throwing such connections into operation to actuate the ex-

tra coin - feed device when the rest of the change-making mechanism is thrown out of operation, substantially as and for the purpose described.

- 5 35. In combination with a register to register purchases of different values, a series of keys connected with such register to actuate the same, a series of sources of supply of coins, a series of feed devices therefor, to feed out 10 coins therefrom, having movable coin-engaging parts adapted to be moved into and out of operative position for engaging the coins, yielding means for holding them normally in operative position, means for moving them, 15 at will, out of such position, and connections between the keys and feeding devices for actuating the latter, substantially as and for the purpose described.

- 20 36. In combination with an indicator, to indicate purchases of different values, a series of keys connected with the indicator to actuate the same, a series of sources of supply of coins, a series of feeding devices therefor for feeding out coins therefrom, each having a 25 movable, coin-engaging part adapted to be moved into and out of operative position for engaging a coin, means for holding the coin-engaging parts normally up, in operative coin-engaging position, means for moving them 30 out of such position, and connections between the keys and coin-feeding device for actuating the latter, substantially as and for the purpose described.

- 35 37. In combination with a register and indicator, to register and indicate purchases of different values, a series of keys connected with the register and indicator to actuate the same, a series of sources of supply of coins, a series of coin-feeding devices for feeding out 40 coins from the different sources of supply, each having a movable, coin-engaging part adapted to be moved into and out of operative position for engaging a coin of its respective source of supply, means for holding such 45 parts in operative position, means for moving them out of such position, and connections between the keys and coin-feeding devices for actuating the latter, substantially as and for the purpose described.

- 50 38. In combination with a rock-shaft, having arms, a series of sources of supply of coins, one for each of the arms on the shaft, a series of coin-feeding devices, one for each source 55 of supply, each having a spring-elevated, pivoted, coin-engaging dog, connected with a slotted piece, into the slot of which one of the arms on the rock - shaft projects, two other sources of supply of coins, the two feed devices therefor carrying pivoted coin-engaging 60 dogs, each having a spring to raise it into operative coin-engaging position, and a slotted piece connected with it, two sleeves journaled on the rock-shaft, each having an arm projecting into the slot of the piece connected 65 with one of the last two mentioned coin-feeding dogs, an operating-arm on the rock-shaft, an arm on one of the sleeves engaging such

arm, and an arm on the second sleeve engaged by the arm on the other sleeve, which engages the operating-arm on the rock-shaft, 70 and means for moving the latter arm, to rock the shaft and sleeves, substantially as and for the purpose described.

- 75 39. In combination with a coin-holder, a movable feed device therefor, having pivoted upon it a coin-engaging dog, a spring for elevating such dog, a piece connected with the dog and having the shoulder to strike a part of the feed device and act as a limit to the raising of the dog by the spring, and a slot, a 80 rocker having a dog-depressing arm extending within such slot, and means for rocking the rocker, substantially as and for the purpose described.

- 85 40. In combination with a series of coin-holders, and a series of feeding devices therefor, each having a pivoted coin-engaging dog and a spring holding such dog normally in position for engaging and feeding out a coin from the respective coin - holder, a slotted 90 piece connected with each dog, depressing-arms engaging the slots in such pieces, rocking means connected with such arms for depressing them, an operating-arm connected with such rocking means to actuate the same 95 to cause the depressing-arms to draw the dogs down out of operative position, a key pivotally connected with the operating-arm, so as to swing it as the key is moved longitudinally, but to be capable of swinging on the 100 arm as a fulcrum, an extra coin-holder, a coin-feeding device therefor having a part to engage and feed out a coin from the extra holder, a reciprocating slide for actuating the feed device, adapted to be coupled with and 105 uncoupled from the device, by movement of part of the slide toward and from the feed device, and means for normally holding the slide uncoupled from the feed device, arranged in the path of an arm of the key so as 110 to be engaged and moved thereby, to cause the slide to become coupled with the feed device as the key is rocked on its fulcrum, substantially as and for the purpose described.

- 115 41. In combination with a series of coin-holders, and a series of coin-feeding devices therefor, each having a movable coin-engaging part adapted to be moved into and out of operative position to engage and feed out a coin from the respective holder, yielding 120 means for normally holding each of such parts in operative position, a rocking piece, connections between the latter and the movable coin-engaging parts on the feed devices, whereby such parts are drawn out of operative position by rocking of the rocking piece, an arm on such piece, a reciprocable and swinging key pivoted on such arm, but prevented from longitudinal movement through 125 or with reference to such arm, a rock-shaft 130 having an arm engaged by the key, so as to be rocked thereby, as the key is swung on its fulcrum on the arm of the rocking piece, a spring normally holding the rock - shaft

against rocking, an extra coin-holder, a feed device for feeding out coins from the same, a shoulder on such device, a reciprocating slide carrying a lug to engage the shoulder 5 on the feed device, when the slide is not raised, and a crank-arm on the rock-shaft engaging the slide and holding it normally raised when the shaft is not rocked by the key, substantially as and for the purpose de- 10 scribed.

42. In combination with the dollar, fifty-cent, twenty-five-cent, ten-cent and regular five-cent holders, feed-slides, one for each holder each having a spring-raised, pivoted 15 coin-engaging dog on it, means for swinging the dogs of all the slides down out of operative position so that they will not engage and feed out any coins as the slides are moved, means for actuating the slides, an extra 20 five-cent holder, a feeding device for the same having a part to engage and feed a coin out of the holder, and a shoulder, a slide connected with the feed-slides for the other holders so as to be moved as any one of them 25 is moved, and having a lug to engage the shoulder on the extra five-cent feed-slide, when the slide carrying the lug is down, and means for normally holding up the lug-carrying end of the slide adapted to be de- 30 pressed, at will, to cause the latter slide to be coupled with the extra five-cent feed-slide, substantially as and for the purpose described.

43. In combination with a series of holders 35 for dollar, fifty-cent, twenty-five-cent, five-cent, and ten-cent coins, and feed devices therefor, for feeding coins out therefrom, cut-out devices to cut out of action all of such feed devices, a cut-out key connected with 40 the cut-out devices for actuating the same, an extra holder for five-cent coins, a feed device to feed the coins out of such holder, means for normally holding the latter feed device out of action, adapted to be engaged 45 and moved, at will, to throw the extra five-cent feed device into action, substantially as and for the purpose described.

44. In combination with a series of holders 50 for coins of different denominations, and feed devices therefor to feed coins out therefrom, means for moving such devices, cut-out mechanism to cut all of such feed devices out of action, a cut-out key connected with such mechanism to actuate the same, an extra coin- 55 holder, a feed device for feeding coins out of such holder, a movable part to actuate the device adapted to be coupled with and uncoupled from the feed device, means for holding such part normally uncoupled from the 60 feed device, adapted to be moved by the cut-out key, to cause the moving part to be coupled with the feed device so as to actuate the same, substantially as and for the purpose described.

45. In combination with a series of keys for 65 causing registration of a series of purchases of different values, a cash-register actuated

by such keys so that as any key is moved registration of the value of the purchase corresponding to that key will be caused, a change-maker having a series of coin-holders for holding dollar, fifty-cent, twenty-five-cent, five-cent and ten-cent coins, respectively, and movable feed devices for feeding coins from such holders, connections between the keys and such devices, whereby, as any key is moved, one or more of the feed devices will be actuated to feed out a coin or combination of coins equal in value to the difference between the amount of the purchase caused to be registered by the movement of the key and a predetermined sum of money, and a cut-out device to cut out of action the coin-feeding device, at will, for the fifty-cent coin-holder, substantially as and for the purpose described. 70 75 80 85

46. In combination with a series of keys for causing registration of purchases of different values, a cash-register connected therewith, so that the motion of any key will cause registration of a purchase corresponding to the key moved, a change-maker having a series of coin-holders for holding dollar, fifty-cent, twenty-five-cent, five-cent and ten-cent coins, respectively, a series of coin-feeding devices 90 for feeding coins out from the holders, connections between the keys and the coin-feeding devices, whereby, as any key is moved, one or more of the coin-feeding devices will be actuated to feed out a coin or combination 95 of coins equal in value to the difference between the amount or value of the purchase caused to be registered by the movement of the key, and a predetermined sum of money, and cut-out devices for cutting out of action, 100 at will, the coin-feeding devices for the fifty-cent and twenty-five-cent coin-holders, so that they will not feed out coins from their respective holders, as they are actuated by the movement of any key or keys, substantially 105 110 as and for the purpose described.

47. The combination of a series of keys for causing indication of a series of purchases of different values, a cash-indicator, having indicator mechanism actuated by such keys so 115 that, as any key is moved, an indication of the value of the purchase corresponding to that key will be caused, a change-maker having a series of coin-holders, for holding dollar, fifty-cent, twenty-five-cent, five-cent, and 120 ten-cent coins, respectively, movable feed devices for feeding coins from such holders, connections between the keys and such devices, whereby, as any key is moved, one or more of the feed devices will be actuated to 125 feed out a coin or combination of coins equal in value to the difference between the amount of the purchase caused to be indicated by the movement of the key and a predetermined sum of money, and a cut-out device to 130 cut out of action the coin-feeding device for the fifty-cent coin-holder, at will, substantially as and for the purpose described.

48. The combination of a series of keys for

- causing indication of purchases of different values, a cash-indicator connected therewith, so that the motion of any key will cause indication of a purchase corresponding to the key moved, a change-maker having a series of coin-holders for holding dollar, fifty-cent, twenty-five-cent, five-cent and ten-cent coins, respectively, a series of coin-feeding devices for feeding coins out from the holders, connections between the keys and the coin-feeding devices, whereby, as any key is moved, one or more of the coin-feeding devices will be actuated to feed out a coin or combination of coins equal in value to the difference between the amount or value of the purchase caused to be indicated by the movement of the key, and a predetermined sum of money, and cut-out devices for cutting out of action, at will, the coin-feeding devices for the fifty and twenty-five cent coin-holders, so that they will not feed out coins from their respective holders as they are actuated by the movement of any key or keys, substantially as and for the purpose described.
49. In a register in combination with a movable frame connected with the registering mechanism, so as to actuate it, a series of movable parts for actuating such frame having frame engaging and actuating abutments, standing at different distances from the frame, when the parts are unmoved, and a series of movable stops, one for each frame-actuating part and unconnected therewith, each adapted to move automatically into the path of a portion of the frame, to act as a limit to the movement of the same, when the respective frame-actuating part is moved in a direction to actuate the frame, substantially as and for the purpose described.
50. In a register, in combination with the registering devices and a moving frame for actuating the same having a transverse bar, a series of reciprocating rods having heads with bar-engaging abutments standing at different distances from the bar of the movable frame when the rods are not reciprocated, and also parts projecting beyond the rear side of the bar, movable stops to limit the movement of the bar of the movable frame, each supported above the path of the bar by a portion of the respective head on a rod, when such rod is in its normal unmoved position, and allowed to drop down into the path of the bar as the head is reciprocated to actuate the bar, substantially as and for the purpose described.
51. In a register, in combination with the registering devices and a moving frame for actuating the same having a transverse bar, a series of reciprocating rods having heads with bar-engaging abutments standing at different distances from the bar, when the heads are unmoved by reciprocation of the rods carrying them, each of such heads having a part extending under the bar and provided, at a point to the rear of such bar, with a raised portion, a series of movable stops to limit

the movement of the bar of the movable frame, there being one stop for each head, and such stop being normally supported in elevated position by the raised portion of such head, and adapted to drop down into the path of the bar, to limit its movement, when the head has been moved toward the bar, substantially as and for the purpose described.

52. In a register, in combination with the registering devices and a moving frame for actuating the same having a transverse bar, a series of reciprocating rods having heads with bar-engaging abutments standing at different distances from the bar, when the rods and heads are unmoved, each of such heads having a part extending under the bar and provided, at a point to the rear of such bar, with a raised part, a series of movable stops, one for each head, to limit the movement of the bar, such stops being normally supported above the path of the bar by the raised parts of the respective heads, before such heads are moved, and adapted to drop into the path of the bar, as their respective heads are moved to actuate the bar, the bar engaging and stopping ends of such stops standing at different distances from the bar, substantially as and for the purpose described.

53. In a register, in combination with the registering devices and a moving frame for actuating the same having a transverse bar, a series of reciprocating rods having heads with bar-engaging abutments standing at different distances from the bar, when the heads are in their normal unmoved positions, each of such heads having a depressed part passing under the bar and, beyond the rear of the bar, a raised part, a series of movable stops to limit the movement of the bar, one for each head, normally supported above the path of the bar by the raised rear parts of the respective heads, when such heads are unmoved, and adapted to drop into the path of the bar, when the portions of the heads supporting them are moved by the travel of the heads to carry their bar-engaging abutments toward the bar, the forward bar engaging parts of such stops being at different distances from the bar, when the latter is in its normal unmoved position, and the stops for these heads whose abutments are farthest from the bar, when the parts are in their normal unmoved positions, being nearest the rear side of the bar at that time, substantially as and for the purpose described.

54. In combination with a register having registering devices and a movable frame for actuating the same provided with a transverse bar, a series of reciprocating rods having heads provided with abutments to engage and actuate the bar, and portions extending under and beyond the bar provided with raised parts to the rear of the bar, movable stops for the bar supported by the raised parts of the heads, when the heads are unmoved, and dropping down into the path of

the bar as the respective heads are moved to actuate the bar, a series of indicating devices, one for each of the heads on the reciprocating rods, having indicator-raising levers 5 each of which has an actuating-arm in the path of the respective head, slotted to admit the passage of the movable stop corresponding to such head, substantially as and for the purpose described.

10 55. In a registering mechanism, in combination with a movable rack and means for moving it in one direction and allowing it to move back again, a register-wheel, a ratchet-wheel connected therewith, a pinion engaged

15 by the rack, an arm moving with the pinion, a pawl on such arm engaging the ratchet-wheel so as to rotate it only as the pinion rotates back, after it has been turned by the rack, a spring, and a cord connected there-

20 with and with a hub rotating with the pinion having a spiral track for the cord wound thereon, decreasing in diameter from the point where the cord is attached to the hub, substantially as and for the purpose described.

25 56. In combination with the rotary pinion and the movable rack meshing therewith to drive it in one direction, a ratchet-wheel having its teeth on its side toward the pinion, an arm rotating with the pinion and having piv-

30 oted to it on a pivot substantially parallel to a radius of the pinion, a spring-pressed pawl engaging the teeth on the ratchet-wheel so as to rotate the same only as the pinion turns back in a direction opposite to that in which

35 the rack rotates it, yielding means for so turning the pinion, and a registering device connected with the ratchet-wheel, substantially as and for the purpose described.

57. In combination with the swinging seg-40 mental rack and a rock-shaft carrying the same, a rotary pinion meshing with the rack, means for moving the rack to rotate the pinion in one direction, means for rotating it in the other direction, an arm moving with the

45 pinion, a ratchet-wheel, a pawl on the arm engaging such ratchet-wheel, so as to rotate it only as the pinion is turned in the direction opposite to that in which it is moved by the rack, a shaft rotating with the ratchet-

50 wheel, a registering device, connections between the same and the shaft, a second ratchet-wheel rotating with such shaft, having its teeth turned to bring their abrupt sides facing in the direction in which such

55 shaft is turned, an arm on the rock-shaft carrying the segmental rack, and a yielding brake-pawl thereon to engage the second ratchet-wheel as the segment-rack returns to its normal position after being actuated to

60 turn the pinion, substantially as and for the purpose described.

58. In combination with the swinging seg-65 mental rack and the rock-shaft carrying the same, a rotary shaft, a pinion journaled so as to rotate thereon meshing with the rack, a ratchet-wheel fixed on such shaft, an arm rotating with the pinion, a pawl on such arm

engaging the ratchet-wheel on the shaft, a second ratchet-wheel fixed on the shaft and having its teeth with their abrupt sides facing 70 in a direction forward, with reference to the rotation of the other ratchet-wheel and the shaft, an arm on the rock-shaft which carries the segmental rack, having a socket and a slot, a stop-pawl to engage the second ratchet- 75 wheel movably held in such socket, a spring in the socket for yieldingly supporting the stop-pawl, and a pin for limiting the motion of this pawl with reference to the arm carrying it projecting into the slot in the arm, sub- 80 substantially as and for the purpose described.

59. In combination with a graduated reg-85 istering-disk carried on a rotating shaft, a second graduated disk carried by a shaft journaled on the disk and carrying a toothed wheel, a fixed support past which the first disk rotates to carry the second disk and toothed wheel past it, a lug on the fixed sup-90 port to engage the toothed wheel to turn such wheel as it is carried past the fixed support 95 by rotation of the first disk, a movable frame in which the shaft carrying the first disk is journaled, a shaft journaled on the fixed sup-90 port, driving-gearing between such shaft and the one carrying the first disk adapted to be 100 thrown into and out of mesh as the movable frame is moved to carry the first disk toward and from the fixed support carrying the pro-jection for engaging and moving the toothed wheel, substantially as and for the purpose 100 described.

60. In combination with a graduated reg-105 istering-disk and means for rotating the same, a second graduated registering-disk carried by the first disk, so as to be capable of rota-tion thereon, a second wheel connected with the second registering-disk, and a projection on a suitable support, past which the first disk rotates, adapted to engage the toothed wheel connected with the second disk, so as 110 to turn the same to the distance of one tooth, at each full rotation of the first disk, substan-tially as and for the purpose described.

61. In combination with a graduated reg-115 istering-disk and means for rotating the same, a second graduated registering-disk attached to a shaft journaled in the first disk, a toothed wheel on the latter shaft and a pro-jection on a stationary support past which the first disk rotates adapted to engage the teeth 120 of the toothed wheel to rotate the latter through the distance of one tooth, at each full rotation of the first disk as such wheel, with the connected second registering-disk is car-ried by the projection by the rotation of the 125 first disk, substantially as and for the purpose described.

62. In a combined cash-register and change-maker, in combination with the registering mechanism for registering purchases of dif-130 ferent values, a change-maker connected with such register, and adapted to issue coins and combinations of coins equal in value to the difference between any purchase registered

and a certain predetermined sum of money, a source of supply of dollar-coins, a feed device for feeding out coins therefrom, means for moving such device, and connections between such means and the registering mechanism, whereby the latter is caused to register a dollar, each time that such means is moved to actuate the dollar-feeding device, substantially as and for the purpose described.

10 63. In a combined cash-register and change-maker, in combination with the change-making mechanism, adapted to issue different amounts of change to equal the difference between the different purchases to be registered and a predetermined sum of money, separate devices for causing the change-maker to issue such different amounts of change, a registering mechanism, connections between the change-maker-actuating devices and such

15 mechanism, whereby the movement of any one of such devices causes registration of the amount of a purchase, as the change-maker

is caused to issue an amount of change equal in value to the difference between such purchase and the predetermined sum of money, 25 a source of supply of dollar-coins, a feed device to feed out coins therefrom, means for connecting such device with, and disconnecting it from the other feed devices of the change-maker, so that, at will, it can be made 30 to operate as any one of such feed devices operates, means for moving the dollar-feed device, without moving the other feed devices and connections between such latter means and the registering mechanism, to cause the 35 latter to register a dollar each time that such means actuates the dollar-feed device, substantially as and for the purpose described.

In testimony whereof I affix my signature in presence of two witnesses.

MICHAEL MCANENY.

Witnesses:

A. J. O'BRIEN,
GRACE MYTINGER.
